MACHINE FOR OPERATING ON THE BACK
PARTS OF SHOE UPPERSLester S. Macdonald, Beverly, Mass., assignor to
United Shoe Machinery Corporation, Flemington,
N. J., a corporation of New Jersey

Application November 7, 1941, Serial No. 418,236

72 Claims. (Cl. 12—97)

This invention relates to machines for operating upon shoe parts and more particularly to machines for shaping the back parts of shoe uppers. The invention is herein illustrated with reference to that type of machine having provisions for molding the back part of a shoe upper substantially to final shape and forming thereon a heel-attaching flange.

In the molding the back parts of shoe uppers with a heel-attaching flange, it is desirable to crimp or corrugate the lasting margin around the heel end prior to forming the flange in order to insure uniform pleating around the heel end when the lasting margin is subsequently turned inwardly to avoid the formation of wrinkles in the outer surface of the upper which would impair the appearance of the finished shoe. To this end and as a feature of the invention the machine herein illustrated includes a work support or inner mold shaped like the heel portion of a last, adjacent to which is a crimping plate arranged to support the overhanging lasting margin of an upper mounted on the support. Wipers cooperate with the crimping plate to perform the lasting margin by forming heightwise corrugations therein after which the crimping plate is retracted to permit the wipers to turn the lasting margin inwardly over the adjacent face of the inner mold.

In order to produce a well-defined heel-seat further to improve the appearance of the finished shoe, it is desirable to stretch the upper slightly relatively to the lasting margin. This is accomplished in accordance with a further feature of the invention by mounting the work support or inner mold for movement relatively to the crimping plate. After the lasting margin has been crimped by the wipers on the crimping plate, the inner mold is moved rearwardly of the shoe which stretches the upper relatively to the lasting margin and produces a well-defined heel-seat line. This movement of the inner mold may also be utilized in accordance with another feature of the invention to stretch an intramarginal portion of the back part during the formation of the heel-seat line. By so stretching an intramarginal portion of the back part, the danger of the back part losing its shape after the molding operation has been completed will be minimized. As herein illustrated, this stretching of the intramarginal portion may be accomplished by providing the inner mold with a movable plug in an intramarginal portion of the heel end. This plug is normally urged to a position in which it extends outwardly of the

inner mold but may be moved inwardly until it forms a continuation of the surface of the mold. When the back part is mounted on the inner mold it will rest on the movable plug and the crimping plate with the portion between these members being unsupported. As the wipers move to crimp the lasting margin on the crimping plate an outer mold clamps the back part on the plug so that upon movement of the inner mold to stretch the back part and form the heel-seat line, that portion of the back part bridging the plug and the crimping plate will also be stretched.

The outer mold may be made in two parts which are hinged together and are arranged to be moved toward each other to apply molding pressure to the sides of the back part. While this type of mold is generally satisfactory, when operating on certain kinds of work a fin or ridge may be formed in the outer surface of the back part along the line between the two parts of the mold which may impair the appearance of the finished shoe. To insure against this, and in accordance with another feature of the invention, the outer mold may be made solid thereby eliminating any joint at the back which might pinch the leather and form a projecting fin or ridge. To permit relative movement of the inner and outer molds to mold the backpart between them, the walls of the solid outer mold are made divergent from the back end of the mold, which is in turn curved sharply to conform to the shape of a last. The sides of the outer mold may be made somewhat yielding so that after the work has been clamped between the inner and outer molds, the sides of the outer mold may be moved inwardly to mold the corresponding portions of the backpart.

To facilitate loading the machine and in accordance with a still further feature of the invention, the inner mold on which the work is supported is mounted for movement from a position in which it underlies the outer mold to a position in which it is out of register therewith. As the outer mold moves downwardly to grip the work between it and the inner mold and to clamp the lasting margin on the crimping plate the inner mold is moved inwardly into the path of movement of the outer mold.

The wipers by which the lasting margin is initially corrugated and later turned inwardly to form an attaching flange are carried for movement with a head which also supports the outer mold, the wipers also being movable relatively to the head. The wipers are normally held in

separated relation as they move with the head but upon relative movement between the wipers and the head they are moved inwardly toward each other. Accordingly, as the head moves the outer mold and wipers toward the inner mold and crimping plate, the wipers initially contact the extreme heel end of the lasting margin, after which they are unable to move as a unit with the head. Accordingly, further movement of the head causes the wipers to move inwardly and close around the crimping plate thereby to grip close around the crimping plate thereby to grip the lasting margin firmly and crimp it.

In accordance with a further feature of the invention, means under the control of the operator are provided whereby the machine may go through its entire cycle of operation automatically, or may be caused to come to rest prior to the stretching operation, to permit the operator to inspect the work.

Various novel features of the invention are further to be recognized in the fluid-pressure means by which the various working parts of the machine are operated, and valves for controlling the flow of fluid under pressure to the fluid-pressure means to cause the parts of the machine to be operated automatically in a predetermined time relation.

The above and other features of the invention, including various novel details of construction and combination of parts, will now be more particularly described by reference to the accompanying drawings and pointed out in the claims.

In the drawings:

Fig. 1 is a front elevation of one form of machine in which the invention is embodied;

Fig. 2 is a side elevation partly in section of the machine shown in Fig. 1;

Fig. 3 is a front elevation partly in section of a portion of the machine, this view being taken on a larger scale than Fig. 1;

Fig. 4 is a section on the line IV—IV of Fig. 3;

Fig. 5 is a sectional view through the lower portion of the machine, illustrating a portion of the fluid-pressure operated mechanism of the machine;

Fig. 6 is a vertical section through an intermediate portion of the machine, illustrating more of the fluid-pressure mechanism, this section being taken at a right angle to that of Fig. 5;

Fig. 7 is a sectional view of the control valves by which each portion of the cycle of operation is started;

Fig. 8 is a front elevation partly in section of the upper portion of the machine illustrating a work piece positioned in the machine and the parts in their initial positions before operation of the machine is started;

Fig. 9 is an exploded view of the mechanism by which the lasting margin of the back part is first crimped and subsequently flanged;

Fig. 10 is a plan view partly in section of the inner mold, the crimping plate and the mechanism for moving the crimping plate toward and away from the mold;

Fig. 11 is a section taken on the line XI—XI of Fig. 4;

Fig. 12 is a section through one of the valves of the machine;

Fig. 13 is a section taken on the line XIII—XIII of Fig. 6 and illustrating the mechanism for operating the distributor valve;

Figs. 14 to 18 inclusive are sectional views taken through the ports A to E respectively of the rotary distributor valves, the valves being in

the positions assumed at the beginning of the cycle of operation;

Fig. 19 is a vertical section through the inner and outer molds, showing a modified form of outer mold;

Fig. 20 is a front elevation of the molds of Fig. 19;

Fig. 21 is a section on the line XXI—XXI of Fig. 19;

Fig. 22 is a vertical section through the upper portion of the machine illustrating a further modification of the invention; and

Fig. 23 is a chart illustrating graphically the sequence of operations of the machine, the letters thereon corresponding to the similarly identified parts of the valves in Fig. 6.

The machine illustrated herein includes a frame composed of a lower casing member or base 10 (Figs. 1 and 2), an intermediate casing member 12 and an upper casing member 14. Since the machine herein illustrated is operated by power through the action of fluid-pressure means, the upper portion of the lower casing member 10 is formed to provide a reservoir or sump for the operating fluid, preferably oil. Seated on the casing 10 and located within the casing 12 is a housing 16 having formed therein a plurality of cylinders to be hereinafter described. The upper casing section 14 supports a vertically slidable head 18 which carries an outer mold 20 (Fig. 4) and a pair of wiper plates 22. The work to be operated upon is supported upon an inner mold 24 which is shaped substantially like the heel portion of a last. The inner mold is mounted at the upper end of a jack 26 arranged for vertical movement, and just rearwardly of the inner mold is supported a crimping plate 28 mounted for rearward movement relatively to the inner mold. The wipers 22 cooperate with the crimping plate 28 upon downward movement of the head 18 to crimp the lasting margin of the back part of a shoe upper which has been placed on the inner mold 24, after which the back part is stretched relatively to the lasting margin and molded between the inner and outer molds as will be more fully described hereinafter. The crimping plate is then moved away from the inner mold to permit further downward movement of the wipers to turn in the flange 50 against the adjacent surface of the inner mold after which pressure is applied by the inner mold and the wipers to mold or set the flange.

The head 18 is provided at its upper portion with extensions or tongues formed by the projecting edges of a plate 30 (Figs. 1, 3 and 9) secured to the head. These tongues are arranged to slide in ways formed between flanges 19 (Fig. 2) projecting laterally from the upper casing member 14 and plates 32 secured thereto. Pairs of spaced ears 34 extending laterally from each side of the head 18 are pivotally connected to the upper ends of vertically extending rods 36 the lower ends of which extend downwardly through the housing 16 (Fig. 5) and are secured by yokes 38 and pins 40 to laterally extending arms 42 of a piston 44. The head 18 is normally maintained in its uppermost position as illustrated in Figs. 1 and 2 by springs 46 surrounding the rods and acting between collars 48 (Fig. 1) secured to the rods and bushings 50 (Fig. 5) having flanges at their upper ends which rest upon the adjacent surfaces of the housing 16 and the casing 14. Near the lower ends of the rods and above the yokes 38 are provided metallic washers 52 between which are interposed washers 54 of felt or

like material. These washer assemblies engage shoulders in the casing 14 and housing 16 to limit upward movement of the head by the springs 46 and to minimize the shock and the noise resulting when the head reaches its upper limit of travel.

The outer mold 20 comprises a pair of mold members 56 (Fig. 3) pivoted at their upper ends by pins 58 (Figs. 3 and 4) to a support 60. The support 60 is in turn secured to a slide 62 by a retractable pin 64 which permits ready removal of the outer mold assembly to permit replacement thereof. The pin 64 is normally held in position (shown in Fig. 4) by a locking pin 66 the lower end of which fits into an annular groove 68 in the pin 64, the pin 66 being vertically slidable in a plate 70 movable with the slide 62 in a slideway formed in the front of the head 18. A spring 72 urges the pin 66 into locking engagement with the pin 64. The slide 62 is formed at the lower end of an upwardly extending rod 74 slidable in a vertical bore formed in the head 18 and provided at its upper end with lock nuts 76 which limit downward movement of the slide 62 relatively to the head. The upward movements of the slide 62 and the outer mold members carried thereby relatively to the head are opposed by compression springs 78 acting between the head 18 and the slide 62.

The outer mold members 56 are normally held apart by a hairpin spring 80 (Fig. 3) the lower ends of which are connected by pins 81 to the mold members so that upon downward movement of the head and of the outer mold, the heel portion of the upper near the back seam will be engaged before the outer mold applies any pressure along the sides of the back part to mold it to the shape of the inner mold. The lower portions of the outer mold are not moved toward each other until sufficient pressure is applied between the inner and outer molds to cause relative movement between the outer mold and the head 18 and compression of the springs 78. The outer surfaces of the mold members 56 have cams 82 formed thereon which cooperate with cam rolls 84 mounted on levers 86 pivoted at 88 to the head 18. These levers are normally held in the positions illustrated in Fig. 3 by tension springs 90 which hold the outer ends of the levers against yieldable stops 92 mounted for sliding movement in the head 18. The stops 92 are provided with reduced upwardly extending shank portions 94 which extend through plugs 96 threaded into the head. Springs 98 acting between the stops 92 and the plugs 96 force the stops downwardly to a position determined by lock nuts 100 threaded onto the upper ends of the shanks 94. As the head is moved downwardly relatively to the outer mold, the cam rolls 84 ride over the cam surfaces 82 to force the lower portions of the outer mold toward each other against the action of the spring 80. This movement of the portions of the outer mold acts to force the sides of the back part against the sides of the inner mold 24 to conform the back part to the shape of the inner mold. To prevent the pressure between the lower portions of the outer mold and the back part from becoming excessive, the levers 86 will yield by compressing the springs 98 which back up the stops 92 thus preventing damage to the back part or to the machine.

The wiper plates 22 (Fig. 4) are carried for downward movement with the head 18 and the outer mold 20 and are also movable relatively to the mold. These wiper plates are pivoted together at 102 (Figs. 4 and 9) and are mounted on a pair of plates 104. The plates 104 have rear-

wardly extending sleeves 106 within which are mounted retractable pins 108 normally urged forwardly by springs 110 (Fig. 4). Handles 112 on the rearward ends of the pins 108 permit their retraction to facilitate replacement of the wiper members on the supporting plates 104.

The supporting plates 104 are provided with circular peripheral grooves 113 (Fig. 9) arranged to fit over correspondingly shaped tongues 114 on a plate 116 arranged for vertical movement relatively to the head 18. The plate 116 is mounted between the head 18 and the plate 30 which is secured to the head by screws 122 (Fig. 8). The plate 116 is connected to the plate 30 for downward movement with the head by pins 124 (Figs. 4 and 9), passing through slots 126 in the plate 30, the pins being normally maintained against the lower ends of the slots by springs 128 acting between the pins 124 and pins 130 in the plate 30. The plate 116 is thus confined between the head 18 and the plate 30 and normally moves downwardly with the head. However, the pin-and-slot connection between the plate 116 and the plate 30 permits downward movement of the head and the outer mold relatively to the plate 116. The wipers being secured by pins 108 to the plates 104 which are in turn mounted for arcuate movement on the plate 116 will move vertically with the plate, these wipers being confined between the plates 104 and the head 18. As shown in Fig. 9, corrugations or ribs 132 are formed part way around the work-engaging surfaces of the wipers to crimp the lasting margin of the upper around the heel end as the wiper members move downwardly to exert pressure on that portion of the lasting margin which overlies the crimping plate 28.

The peripheral portions of the wiper-supporting plates 104 are provided with teeth 134 which mesh with rack teeth 136 at the lower portions of gear racks 138. These racks are confined between the outer edges of the plate 116 and the contiguous portions of the head 18 and the plate 30, but are arranged for vertical sliding movement relatively to the head. On the same side of the racks 138 as the teeth 136 are second sets of rack teeth 140 arranged for engagement with gears 142 having pivots 144 passing through bearings 146 in the plate 116. The gears 142 also engage teeth 148 on a floating rack 150 arranged to slide between tongues 152 and 154 on the plate 116. The upper rearward sides of the racks 138 are provided with third sets of rack teeth 156 which mesh with gear segments 158 mounted on the forward ends of arms 160 which pass through slots 162 in the plate 30. The arms 160 are each U-shaped when viewed in plan as indicated in Fig. 9 and embrace rearwardly extending bearing members 164 on the plate 30 to which they are pivoted. The adjacent legs of the U-shaped arms carrying the gear segments are connected together by a web 166 so that the segments will move as a unit.

The adjacent portions of the arms 160 extend upwardly to form bearings 168 (Fig. 4) in which is journaled a shaft 170 supporting a slide 172. This slide embraces an upwardly extending arm 174 mounted on the forward end of a rod 176 slidably mounted in a bearing 178 in the upper casing member 14. This construction permits downward movement of the head 18 with its plate 30 carrying the gear segments 158 as a unit relatively to the rod 176 while permitting pivotal movement of the gear segments relative-

ly to the head upon sliding movement of the rod 176.

When the head 18 is first moved downwardly from the position shown in Figure 4, the plate 116 carrying the wiper members and associated parts will move with the head as a unit as long as no resistance to such movement is encountered. During this time the slide 170 connected to the gear segments 158 will move downwardly relatively to the arm 174 extending upwardly from the rod 176. The wiper members 22 are so held during the initial downward movement, as will be later described, that they will initially contact only the extreme back part of the lasting margin of the upper which overlies the crimping plate 28. The crimping plate is so arranged relatively to the inner mold 24 that the lasting margin is engaged by the wipers before that portion of the back part overlying the inner mold 24 is engaged by the outer mold. After the wipers have thus engaged the lasting margin they will not move further downwardly as the head continues to descend so that the head and the plate 30 secured thereto will descend relatively to the plate 116 carrying the wipers. During this time, however, the gear segments 158 carried by the plate 30 fast to the head will continue to descend, thus moving the racks 138 downwardly relatively to the wiper-supporting plate 116. This downward movement of the racks 138 will cause the wiper-supporting plates 104 to move arcuately on the plate 116 so that the lower portions of the wipers will approach each other thereby to clamp the lasting margin along the sides of the crimping plate 28 and to conform the lasting margin to the crimping plate. The floating rack 150 which engages the adjacent portions of the gears 142 will be caused to move upwardly in response to downward movement of the racks 138, such upward motion being transmitted to the floating rack through the gears 142. The function of this center floating rack will appear as the description proceeds. It will thus be apparent that as the head descends to move the wipers and the outer mold into engagement with the work supported on the crimping plate and the inner mold, the lasting margin will first be clamped between the crimping plate and the wipers and then the plate 30 carried by the head will move downwardly relatively to the plate 116 carrying the wipers so that the pins 124 which pass through the slots 126 in the plate 30 will no longer be seated in the bottoms of these slots. Downward movement of the outer mold and head as a unit relatively to the wipers during the first part of the cycle of operation of the machine continues until a surface 178 (Fig. 4) on the inner end of the slide 62 engages an adjacent surface of the wipers.

The position of the wipers when the machine is at rest is determined by the position of the rod 176 (Fig. 4) by which movement is later imparted through the gear segments 158 to the racks 138. This rod extends rearwardly outside of the casing 14 and passes through a cap 180 secured to the rear portion of the casing 14. The rearward end of the rod is reduced at 183 and a collar 185 provided with a flange 187 is mounted on the reduced portion. A spring 182 confined between the flange on the collar and nuts 184 threaded onto the outer end of the rod maintains the shoulder on the rod 176 in contact with the reduced portion 183 in contact with the flange on the collar 182. A bell crank lever

186 (Fig. 4) is pivoted at 188 to the casing 14, the upper arm of this bell crank lever being pivotally connected by a crosshead 190 to the rod 176. The other arm of the bell crank lever is urged downwardly by a pair of springs 192 connected between the bell crank lever and a pin 194 secured to the frame of the machine. The springs 192 urge the rod forwardly of the machine and maintain the flange 187 of the collar 185 in engagement with the cap 180. These springs are of less capacity than the spring 182 which is thus effective to maintain the shoulder of the rod in engagement with the flange of the collar in the absence of a force additional to the force of the springs 192 acting on the rod, so that the rod assumes the position illustrated in Fig. 4 with the wipers in open positions when the machine is at rest.

The extreme upper end of the head 18 is slotted at 196 (Figs. 3 and 8) and the upper end of this slot is closed by a block 198 secured to the head by screws 200. An adjustable stop screw 202 is threaded through the block in alignment with the floating rack 150 (Figs. 4 and 8) and acts by engagement with the top face of the floating rack 150 to limit its upward movement as the racks 138 are being moved downwardly in response to forward movement of the rod 176 (Fig. 4). Pivoted to the block 198 is a latch 204 (Fig. 9) which is normally urged inwardly of the machine by springs 206 having their upper ends secured by pins 208 to forwardly extending arms of the latch 204. The lower ends of these springs are secured to pins 210 secured to the block 198 so that these springs urge the latch in a counterclockwise direction as viewed in Fig. 4 from the position illustrated. When the head 18 is in its uppermost position the latch 204 is held in the position illustrated in Fig. 4 against the force of the springs 206 by engagement of a rearwardly extending arm 212 secured to the latch with the under surface of a bracket 214 secured to the top of the casing 14. Upon downward movement of the head 18 the arm 212 moves out of engagement with the bracket 214 so that the latch is moved rearwardly to its locking position by the springs 206. When the latch is in its normal position, its lower end is arranged to engage a notch 216 (Fig. 9) formed in the upper portion of the rack 150 so that the rack will be held by the latch in its uppermost position after it has been moved thereto through the action of the racks 138, the purpose of which will appear more fully hereinafter.

Carried by the latch are a pair of rearwardly extending screws 220 (Fig. 9) on which are slidably mounted sleeves 222 (Fig. 4) urged rearwardly by springs 224 confined between the forward ends of the sleeves and the back surface of the latch. These sleeves form resilient abutments arranged to be engaged during a certain part of the cycle of operations of the machine by the slide 172 upon forward movement of the rod 176 to move the latch out of engagement with the rack 150.

The inner mold 24 and the crimping plate 28 are mounted at the upper end of the jack 26, the lower end of which is connected to a piston 230 by a T-slot connection 231 (Figs. 3 and 5). This piston is slidably in a cylinder 232 (Fig. 4) formed in the upper part of the housing 16. When the machine is in its loading position, the jack and piston are held by gravity in the positions illustrated, these positions being determined by the adjustment of a wedge 234. This wedge

is adjustably secured to the casing 14 by a screw 236 the body portion of which extends through an elongated slot 238 in the wedge and is threaded into the casing 14. The wedge has an inclined surface 240 on which a similarly inclined surface of the jack 26 rests when the jack is in its lowermost position. To prevent any rotative movement of the jack and the piston relatively to the cylinder 232 the piston is provided with flat surfaces 239 (Figs. 4 and 5) at opposite sides thereof with which engage plates 241 (Figs. 3 and 5) having downwardly extending portions 242 secured by screws 244 to the outside wall of the cylinder 232. These plates cooperate with the shoulders formed by the flat surfaces 239 to limit upward movement of the piston 230 and the jack 26.

The inner mold 24 has a tongue-and-groove connection 245 with a rearwardly extending supporting plate 246 (Figs. 4 and 10) this plate in turn having a horizontal tongue-and-groove connection 247 with the upper end of the jack 26. The lower portion of the mold 24 has an aperture 250 which receives a spring-pressed detent 252 (Figs. 4 and 9) on the supporting plate 246 removably to secure the inner mold thereon. To facilitate removal of the inner mold from the supporting plate 246 a slidable pin 254 is mounted in the mold 24 in alignment with the spring-pressed detent 252 to facilitate moving the detent rearwardly out of locking engagement with the mold.

At the forward edge of the inner mold 24 is mounted a gage plate 256 for facilitating positioning of the back part on the inner mold with its back seam centrally disposed thereon. The gage plate 256 is mounted on a pin 253 adjustably held in a bore in the mold 24 (Fig. 4) by a set screw 255. The gage plate 256 may also serve if desired to determine the heightwise position of the back part on the mold.

The crimping plate 28 straddles the inner mold-supporting plate 246 (Fig. 9) so that it may move rearwardly with respect to the mold 24 from the position of Figure 4. This crimping plate has a tongue-and-groove connection 261 with a supporting member 260 (Fig. 4). Adjustably secured to the upper surface of the supporting member 260 by a screw-and-slot connection 262 is a plate 264 which forms a support for a gage plate 266. This gage plate (Fig. 10) is yieldingly mounted on the supporting member 264 by a pair of pins 268 passing rearwardly through the supporting member 264 and being threaded at their rearward ends to receive nuts 270. Springs 272 are positioned between the gage plate 266 and the supporting member 264 to urge the gage plate forwardly to a position determined by the nuts. This gage plate serves to locate the lasting margin on the crimping plate and may yield rearwardly if necessary during the crimping operation when the wiper plates 22 exert pressure on the lasting margin.

The supporting member 260 is provided at its rearward end with a T-shaped tongue 274 (Fig. 10) which fits into a vertical, correspondingly shaped slot in the forward portion of a cylinder housing 276. The supporting member is rigidly secured in position to the forward portion of the cylinder housing by screws 278 (Figs. 4 and 9) so that the cylinder housing, the supporting member 260 and the crimping plate will move rearwardly as a unit. The cylinder housing is provided with pairs of tongues 280 and 282 which are received for sliding movement by

grooved portions 284 and 286 respectively of the machine frame. This construction permits forward and rearward movement of the cylinder housing 276 while preventing vertical movement thereof.

This cylinder housing is normally maintained in a forward position as shown in Fig. 4 by a spring 288 connected between the rearward portion of the cylinder housing and the pin 194 in the frame.

10 The cylinder housing encloses a double piston member 290 (Fig. 4) having a large piston 292 and a small piston 294 received by cylindrical portions 296 and 298 respectively of the cylinder housing 276. The forward end of the piston member 290 has a vertical T-shaped slot 302 (Fig. 10) for receiving a correspondingly shaped tongue 304 (Fig. 4) of the supporting plate 246 for the inner mold. Thus the inner mold and the piston member 290 are locked together

20 against relative horizontal movement whereas vertical movement of the inner mold relative to the piston member and the crimping plate 28 is permitted. The piston member 290 is slotted at 306 near the forward portion to receive cylindrical members 308 at the lower end of an arm

25 310 (Figs. 4 and 10), the upper end of which is pivoted at 312 to an arm 314 depending from the bearing 178. Between the ends of the arm 310 there is pivoted a rod 316 which extends

30 through a bushing 318 engaging the outer surface of the frame, the rod being threaded at its outer end to receive nuts 320 which engage the outer surface of the bushing to prevent movement of the rod forwardly of the machine. Thus,

35 movement of the arm 310 forwardly of the machine or to the left as viewed in Figure 4 is prevented so that the piston member 290 is constrained against movement forwardly of the machine from the position of Figure 4. A spring 322

40 positioned between the cylinder housing 276 and the piston member 290 urges the piston member rearwardly of the cylinder housing but when the machine is at rest the cylinder housing is maintained by the spring 288 in the position

45 shown in Figure 4, in which position the crimping plate is adjacent to the inner mold 24.

Provision is made for holding the lining of the back part tight after the back part has been placed on the inner mold 24 to prevent wrinkling

50 of the lining during the molding operation. Also, by applying a heightwise tension to the lining relatively to the upper, the top edge of the upper is pulled tightly against the mold and curled inwardly sufficiently to hide the top edge of the lining.

55 For this purpose the sides of the crimping plate at their lower portions are provided with vertical grooves 329 (Fig. 9) with which cooperate gripper jaws 330 adjustably secured by screws 332 to blocks 334 which are pivoted at

60 336 to the member 260 supporting the crimping plate. Spring-pressed plungers 338 (Figs. 9 and 10) interposed between the forward edge of the cylinder housing 276 and the rearward surface of the blocks 334 urge the blocks in a direction

65 to move the gripper jaws toward the crimping plate. Provision is made, however, for holding the jaws away from the crimping plate as indicated in Fig. 10 when the machine is at rest.

Depending from the blocks 334 which support the gripper jaws are rearwardly converging flanges 340 the rearward portions of which engage latches 342 (Figs. 3 and 8) to prevent movement of the gripper jaws toward the crimping plate when the latches are in the positions illustrated in Figure 3. These latches are formed

on the inwardly extending arms of bell crank levers 344 (Fig. 8) pivoted at 346 to arms 348 rigid with the frame of the machine. Springs 350 act between plates 352 secured to the arms 348 and upwardly extending arms of the bell crank levers to urge the latches 342 into latching position. Forwardly extending arms or thumb pieces 354 on the bell crank levers 344 facilitate moving the latches 342 out of engagement with the flanges 340 of the gripper-supporting blocks so that the spring plungers 338 (Fig. 9) acting on the gripper-supporting blocks 340 are effective to move the grippers toward the crimping plate and to grip a lining which has been inserted between the gripper jaws and the crimping plate to hold it firmly on the crimping plate. Upon release of the latches, their upper surfaces will engage the under surfaces of the flanges 340 as shown in Fig. 8. During the operation of the machine, as will be later described, the crimping plate and the latches are moved rearwardly of the inner mold 24. The work is firmly held at this time between the inner and outer molds and the grippers slide over the lasting margin and out of contact therewith. The flanges 340 are more widely spaced at their forward portions than at their rearward portions, and move out of the way of the latches 342 during rearward movement of the grippers. The latches will accordingly be returned by the springs 350 to the positions of Fig. 3. Accordingly, upon movement of the crimping plate and grippers forwardly to their initial positions, the latches will act on the flanges 340 to open up the grippers in readiness for another cycle of operation.

The inner mold 24 and the crimping plate 28 are in the positions illustrated in Fig. 4 during the first part of the cycle of operations of the machine, the crimping plate underlying the wipers 22 so that the lasting margin of the back part is crimped by downward movement of the wipers to facilitate subsequent turning in of the flange. At the proper time in the cycle, the crimping plate is moved rearward relatively to the inner mold 24 to permit further downward movement of the wipers to turn in the flange against the rearward portion of the inner mold. This rearward movement of the crimping plate is effected, as will be later described, by the action of fluid under pressure in the chamber between the rear end face of the small piston 294 and the rear closed end of the cylinder housing 276, the operating fluid being admitted into the chamber through a tube 366 and acting to move the cylinder housing 276 and the crimping plate rearwardly since the piston 294 is at this time constrained against forward movement by reason of its connection to the plate 246 supporting the inner mold. It will be understood that the inner mold is at this time in pressure engagement with the outer mold 20 thus effectively preventing forward movement of the plate 246 and the piston member 290. In order to permit rapid rearward movement of the cylinder housing 276, provision is made for allowing any of the pressure fluid in front of the large piston 292 to flow into the space rearwardly of the large piston. This latter space is connected by a pipe 368 to the oil reservoir in the base 10. To permit flow of fluid from the space in front of the piston 292 to the space rearwardly thereof, ports 370 and 372 connected by a passageway 374 are formed in the large piston member. Flow of fluid through the passageway 374 con-

necting the ports is controlled by a slide valve 376 located in a bore 378 extending through the large and small pistons. A valve actuating member 380 is located in the small piston and is connected by a reduced stem 382 to the valve. The valve is urged rearwardly to closed position by a spring 384 seated in a counterbore in the slide valve, its forward portion engaging a shoulder in the end of the valve chamber. As soon as fluid under pressure is admitted to the chamber in back of the small piston 294 to move the cylinder housing 276 rearwardly, the pressure also acts on the outer end of the member 380 to force the valve forwardly into open position so that the operating fluid in front of the large piston may flow through it and through the pipe 368 to the sump to permit rapid movement of the cylinder housing to move the crimping plate rearwardly of the inner mold. After the crimping plate has been retracted, the wipers move downwardly and turn in the flange against the rearward surface of the inner mold, after which pressure is applied, as will be described, through a tube 390 into the chamber in front of the large piston. At this time the pressure through the tube 366 will be cut off so that the valve 376 is moved toward the right (Fig. 4) under the influence of the spring 378 to close the passageway between the ports 370 and 372 in the large piston. The cylinder housing and the crimping plate are now moved forwardly until the crimping plate engages the wipers. As the pressure in front of the large piston continues to build up after the crimping plate has been forced against the wipers, the pressure between the inner mold and the outer mold is reduced somewhat, as will appear hereinafter, so that the piston 292 is then moved rearwardly to force the inner mold toward the wipers, thereby causing molding pressure to be applied to the inwardly turned marginal portion or flange of the upper.

Initial downward movement of the head 18 to move the outer mold and wipers into engagement with the inner mold and the crimping plate, respectively, is effected by a pair of small pistons 392 and 394 (Fig. 5). These pistons are movable in cylinders 396 and 398 in the housing 16 and are connected by rods 400 to the arms 42 of the piston 44. The lower ends of the rods 400 are flanged at 402 and are received in T-slots in the upper surfaces of the arms 42. Flow of fluid under pressure to the chambers above the pistons 392 and 394 causes downward movement of the large piston 44 which, through its connection to the head 18 by the arms 36, moves the head downwardly against the force exerted by the springs 46. Fluid under pressure is supplied above the small pistons through pipes 404 connected to the outlets of a valve 406. This valve has an inlet 408 (Fig. 7) connected by a pipe 410 to the high pressure side of a pump 414 (Fig. 2) located in the lower casing member 10. The valve 406 includes a valve sleeve 416 which, when in the position shown in Fig. 7, permits oil to flow from the pump through the valve inlet 408 (Fig. 7) directly back to the sump in the casing 10 through ports 418 and pipe 420. This makes it impossible to build up any pressure through the passage of oil outwardly through the valve outlets 422 and pipes 404 to the pistons 392 and 394 so that the head is maintained in its uppermost position by the springs 46. However, upon movement of the sleeve 416 to the right (Fig. 7), communication

between the ports 48 and the sump through pipe 420 is cut off and pressure is applied through the pipes 404 to the pistons 392 and 394 to move them and the head downwardly.

The valve sleeve 416 is connected by a link 424 (Fig. 6) to an arm 426 the upper end of which is secured to a cylindrical member 428 journaled in a housing 430 (Fig. 7). The member 428 is rocked in a counterclockwise direction to move the sleeve 416 to the right upon depression of a treadle 432 pivoted on a rod 434 in the base of the machine. The rearward end of the treadle is pivoted at 436 to an upwardly extending rod 438. This rod extends upwardly through a pipe 440 which is threaded into the bottom wall of the casing 10 (Fig. 5) to prevent leakage of oil from the casing around the treadle rod. The upper end of the rod 438 fits into and is secured to a cap 442 slidable over the pipe 440 and to the cap is connected an upwardly extending arm 444. This arm has a shoulder 446 acting as a pawl to impart a rocking movement to a ratchet 448 secured by a screw 450 to the outer end of the cylindrical valve-actuating member 428. It will thus be seen that upon depression of the treadle 432 the rod 438 will move upwardly and act through the cap 442 and the pawl 446 to move the ratchet 448 in a counterclockwise direction, as viewed in Fig. 6, whereupon the valve sleeve 416 will be moved toward the right (Figs. 6 and 7) to admit fluid under pressure to the chambers above the pistons 392 and 394 to cause downward movement of the head 18. The ratchet 448 is normally maintained in the position illustrated in Fig. 7, by a torsion spring 452 one end of which is secured to the ratchet and the other end of which engages a pin 454 fixed to the frame of the machine. This pin also forms a stop to limit the clockwise movement of the ratchet under the influence of the torsion spring normally to hold the valve sleeve 416 in the position shown in Fig. 7. A latch 456 pivoted to the frame of the machine at 458 engages a shoulder 460 on the ratchet 448 after the ratchet has been rocked to move the valve sleeve to the right so as to hold the sleeve in this position without requiring the operator to maintain his foot on the treadle. This latch 456 is urged by a spring 462 into latching position.

The upper end of the latch 456 has a lost motion connection 464 with one end of a link 466, the other end of which is pivoted at 468 to the upper end of the arm 444. As the latch is moved by the spring 462 into locking engagement with the ratchet 448, a screw 470 in the upper end of the latch moves from one end of a slot in the link 466 toward the left into engagement with an abutment screw 472. Accordingly, when the link 466 is moved toward the right it will move the latch out of engagement with the shoulder 460 on the ratchet, thereby permitting movement of the valve sleeve 416 into the position illustrated in Figs. 6 and 7 to relieve the pressure above the pistons 392 and 394. Provision is made for moving the latch into unlocking position at any time during the operation of the machine should it be desired to return the parts to their original positions for any reason before the completion of the cycle of operations. For this purpose a treadle 474 is pivoted on the rod 434 supporting the treadle 432 and its rearward end underlies an arm 478 extending forwardly of the machine from the treadle rod 438. Upon depression of the treadle 474 the arm 478 will be swung upwardly about the pivot 436 at the inner end of the

treadle 432, thereby causing the treadle rod 438 to be swung in a clockwise direction. This movement of the treadle rod will cause movement of the arm 444 extending upwardly from the cap 442 secured to the treadle rod to the right, thus moving the link 466 to the right and retracting the latch 456. A link 480 is also connected to the upper end of the arm 444 and is connected to mechanism to be hereinafter described for automatically retracting the latch 456 at the completion of the cycle of operations of the machine to cause the return of the various parts to their initial starting positions.

As the head is moved downwardly by the application of pressure above the pistons 392 and 394 the large piston 44 (Fig. 5) moves downwardly away from the piston 230 carrying the jack 26. To permit immediate upward movement of the piston 230 upon the application of pressure thereto and to prevent creation of a partial vacuum between the pistons 44 and 230 provision is made for admitting oil between the pistons during the descent of the head. Oil is drawn from the sump into the space between the pistons 25 during the descent of the head through a pipe 482 (Figs. 5 and 6), and a valve 484 (Fig. 6). This valve includes a vertically movable slide valve member 486 in the form of a cup having an open upper end and a closed lower end and 30 having ports 488 in the sides thereof near the lower closed end. A spring 490 interposed between the lower end of the slide valve member and a cap 492 secured to the upper end of the valve housing by screws 494 (Fig. 5) maintains 35 the valve member seated in the bottom of the valve chamber to prevent flow of the operating fluid through a port 496 during the descent of the head. The oil is drawn upwardly through the pipe 482, passageways 498 and 500 (Fig. 5), a port 502 near the upper end of the valve housing, and thence downwardly through the valve member 486, ports 488 and a passageway 503, which communicates with the ports 488 and the cylinder 232 below the piston 230 so that the space between 40 the pistons 230 and 44 will be maintained full of oil as the head descends. The piston 44 is hollow and slides over a pipe 504 secured by screws 506 (Fig. 5) to the bottom of the casing 10, the pipe being provided with apertures 508 so that 45 the oil may flow thereto. This pipe forms a guide for the piston 44 and being in communication with the sump prevents building up of pressure within the piston during its descent. 50

After the head has descended and the last margin has been gripped by the wipers 28 and the back part has been clamped between the inner and outer molds, the machine may be caused to come to rest to permit the operator to inspect the work, after which the operator may start 55 the machine again to complete the molding operation, or the machine may continue through its cycle of operations without any pause. Further operation of the machine is initiated by movement of a slide valve member 510 (Fig. 7) 60 to the right to permit oil under pressure to flow from the pump 414 through the pipe 410 upwardly into a distributor chamber 512. To the right end of the valve member 510 is pivoted one end of a link 514, the other end of which is pivoted 65 to one arm of a bell crank lever 516 (Figs. 2 and 6) which is pivoted to the frame of the machine at 518. The other arm of the bell crank lever has pivotally connected to it a link 520 which is in turn pivotally connected to an upwardly extending rod 522 guided for vertical

movement in a boss 524 (Fig. 2) on the frame of the machine. The lower end of the rod 522 is connected to the link 520 by a member 526 clamped to the rod and underlying the boss 524. This member forms a stop to limit upward movement of the rod 522. The rod is urged upwardly by a spring 528 confined between a portion of the frame of the machine and the upper end of the rod normally to hold the valve 510 in the position illustrated in Fig. 7. The action of the spring 528 may be augmented by a spring 529 (Fig. 6) connected between the bell crank lever 516 and the frame of the machine at 531 further to insure that the valve will normally be held in this position. When in this position the oil within the distributor chamber 512 is permitted to pass to the sump by way of a port 530 in the valve and a pipe 532. Downward movement of the rod 522 to move the valve 510 to the right is caused by movement of a lever 534 (Fig. 2) pivoted on a shaft 536 rotatably mounted in the casing 14. The forward end of the lever 534 is provided with a hand grip 538 by which the operator may move the lever 534 downwardly if the second part of the cycle of the machine is to be initiated manually. The rearward end of the lever is connected by links 540 and 542 to an arm 544 fast on the shaft 536. An arm 545 also fast to the shaft 536 is connected by a link 546 to one end of a bell crank lever 548, the other end of which is connected to the upper end of a link 550. The lower end of this link is pivoted at 552 to the upper end of the rod 522. Upon counterclockwise movement of the arm 545 a downward force is exerted on the rod 522 to move the valve 510 to the right. The link 542 connected to the upper end of the arm 544 has an upwardly extending projection 554 for engagement with the undersurface of a bracket 556 secured to the side of the housing 14. Engagement of this portion of the link 542 with the bracket during the first part of the downward movement of the lever 534 prevents relative movement of the links 540 and 542 so that they, in effect, form a rigid connection between the lever 534 and the arm 544. Accordingly, during the first part of the movement of the lever 534, movement will be imparted to the arm 544, shaft 536 and arm 545 to connect the pipe 410 and the distributor chamber 512 to operate the valve 510. After sufficient movement has been imparted to the arm 544 thus to move the valve, the extension 554 of the link 542 moves into a recess 560 in the bracket 556 which permits further movement of the lever 534 without imparting any movement to the arm 544 inasmuch as the links 540 and 542 will collapse and no longer serve as a rigid connection between the lever and the arm. This prevents damage to the valve or to the machine should the lever 534 be moved downwardly farther than necessary.

When it is desired to eliminate the pause and have the cycle of operations continue automatically, the lever 534 is actuated during the final downward movement of the head 18 by the pistons 392 and 394. A bracket 562 (Fig. 3) is secured to the lever 534 and is provided at its upper end with a boss 564 for slidably supporting a pin 566. When the pin is in the position shown in Fig. 3 it is located in the path of movement of a rod 568 depending from the head so that during the final portion of the downward movement of the head the lever 534 will be moved downwardly by engagement of the rod 568 with the pin 566. If, however, it is desired to stop the

machine at this time, the pin 566 may be retracted or moved to the right as viewed in Fig. 3 and then turned so that a shoulder 570 at the right end thereof engages a shoulder 572 on the boss 564 to hold the pin out of the path of movement of the rod 568 carried by the head.

The distributor 512 (Figs. 6 and 7) includes three upwardly extending fluid passageways 580, 582, and 584. The passageway 582 communicates through a pipe 586, a valve 588 (Figs. 2 and 12), and a pipe 590, with a fluid-actuated motor 592 for turning at a predetermined rate a pair of rotary valves 594 and 596 (Fig. 6). The valve 588 through which the fluid passes to the motor 592 is illustrated in detail in Fig. 12 and includes a passageway 600, the rate of flow through which is controlled by a valve member 602. A second passageway 604 bypasses the valve member 602 and includes a check valve 606 urged to closed position by a spring 607. When fluid under pressure passes through pipe 586, the spring is effective to maintain the check valve closed. Accordingly, the passageway 600 affords the only path for fluid pressure to the motor 592 and the rate of flow to the motor is thus readily controlled by the valve member 602 by turning it to restrict the passageway as desired. However, upon completion of the cycle of operations of the machine and the release of pressure in the pipe 586 by movement of the valve 510 to the position illustrated in Fig. 7, the pressure behind the check valve 606 is relieved so that this valve is opened by the pressure at the opposite side in the pipe 590 against the action of the spring 607 inasmuch as the pressure in the large pipe 586 will drop more rapidly than the pressure in the passageway 600, thereby permitting rapid release of pressure through the valve 588 from the motor 592.

The motor 592 comprises a cylinder 610 (Figs. 6 and 13) containing a piston 612, biased toward the left, as viewed in Fig. 13, by a spring 614 confined between the piston and a plug 616 at the opposite end of the cylinder secured thereon by a collar 618. The plug 616 provides communication between the interior of the piston and the sump, so that there will be no change in pressure within the piston as it is moved within the cylinder. The pipe 590 is connected to the cylinder by a fitting 620, secured thereon by a collar 622. Upon movement of the valve member 510 to the right (Fig. 7) and flow of pressure fluid through the valve 588 and pipe 590 to the cylinder 610, the piston 612 is moved toward the right (Fig. 13) against the force of the spring 614. This movement of the piston is slow, the rate of such movement being controlled by the setting of the small valve member 602 of the valve 588.

The upper surface of the piston 612 is formed with rack teeth 624, which engage a gear 626 pinned to a shaft 628 extending rearwardly from the rotary valve member 596 (Fig. 6). The rotary valve 596 is connected to the valve 594 by an Oldham coupling 630, whereby these two valves are turned, as a unit, by movement of the piston 612 of the motor 592.

The rotation of the valves 594 and 596 controls the remaining steps in the cycle of operations of the machine, as will be presently described. At the conclusion of the remaining steps in the cycle the latch 456 (Fig. 6) is automatically retracted by the following mechanism, thereby releasing the ratchet 448, which causes movement of the parts of the machine to their initial positions by moving the valve sleeve 416 back to the position shown

in Fig. 7. For thus retracting the latch 456, the gear 626 rotated by the piston 612 includes a hub portion 630 to which is adjustably secured a cam 632 by a screw 634. This cam engages the upper end of a rod 636 mounted for vertical sliding movement in a bracket 638 which supports the shaft 628 and forms the end of the chamber of the valve 596. The lower end of the rod 636 engages an adjustable screw 640 in an arm 642 pivoted at 644 to the bracket 638. The lower end of the arm 642 is pivoted at 646 to the rear end of the link 480. A spring 648 connected between the bracket 638 and a pin 650 secured to the arm 642, maintains the arm in such a position that the screw 640 engages the lower end of the rod 636 at all times. When the piston 612 has moved a predetermined amount, the cam 632 depresses the rod 636, thereby causing movement of the links 480 and 466 toward the right to move the latch 456 out of engagement with the shoulder 460 of the ratchet 448.

As soon as the valve 510 (Fig. 7) has been moved to the right to permit flow of fluid under pressure into the distributor chamber 512, the jack 26 starts to move upwardly, causing a similar movement of the inner mold 24, and the head 18 moves downwardly, compressing the springs 78. Oil flows from the distributor chamber 512 through the passageway 580 to a peripheral groove 652 in the valve 594. The groove 652 provides constant communication by way of a port F with a pressure chamber 654 of the rotary valve member 594. With the valve in its starting position, as shown more clearly in Fig. 14, the pressure chamber 654 is in communication by way of a port A and an annular groove 656 with the port 496 below the valve 484. The slide valve member 486 is accordingly moved upwardly against the force of the spring 490, thereby permitting communication between the passageway 496 and the passageway 503 leading to the space between the pistons 44 and 230. At the same time, the port 502 of the valve 488 which provides communication with the pipe 482 leading to the sump is closed, so that full pressure is now delivered to the underside of the piston 230. The jack 26 now moves upwardly, which causes upward movement of the inner mold 24 (Fig. 4) relatively to the crimping plate 28. The upper mold is moved upwardly by the inner mold against the force exerted by the springs 78. This will cause the back part to be stretched relatively to the lasting margin, which is confined between the crimping plate 28 and the wipers 22, thereby to define the heel seat line. As the inner mold 24 moves upwardly, the pressure also acts upon the piston 44 connected to the head 18, causing downward movement of the head and compression of the springs 78, to increase the pressure between the inner and outer molds, thus permitting only a slight upward movement of the outer mold during the upward movement of the inner mold. Thus, the upward movement of the inner mold and the downward movement of the head cause a heavy molding pressure to be exerted on the work. During the downward movement of the head, the cam rolls 84 carried therewith act on the cam surfaces 82 of the outer mold members to move these members inwardly to mold the sides of the back part to the shape of the inner mold.

Heavy pressure is applied at this time to the wipers 22 through the racks 138 and the gear segments 153. The lower arm of the bell crank lever 186 (Fig. 4) is connected by a pair of rods 660 to a yoke 662 (Fig. 11). This yoke is in turn

secured by a nut 664 to the upper threaded portion of a rod 666 provided at its lower end with a pair of piston members 668 and 669 mounted for vertical movement in a cylinder 670 located above the chamber of the valve 594. The upper end of the cylinder 670 is enclosed by a cap 672 from which extends upwardly a pin 674 (Figs. 4 and 6), confined between a pair of ears 676 projecting laterally from the yoke 662, thereby to prevent turning of the yoke and the pistons.

At the beginning of the flanging part of the cycle of operations of the machine, the space below the lower piston 669 is in communication with the sump. This space communicates by way of a passageway 680 (Figs. 6 and 15) and a port B' (Fig. 15) with a chamber 682 in the valve 594, which chamber forms a discharge chamber which is in communication at all times by way of a passageway 684 (Fig. 6) with the sump. The cap 672 which encloses the upper portion of the cylinder 670 (Fig. 11) is provided with a recess 686 which provides communication between the space above the upper piston 668 and a vertical passageway 688 in the wall of the cylinder. The lower end of the passageway 688, is in communication at this time by way of a port 690 and a port C in the valve 594 as indicated in Figs. 11 and 16 with the pressure chamber 654 so that pressure is applied above the upper piston 668. The pistons accordingly move downwardly thereby pulling the rods 660 downwardly and moving the rod 176 (Fig. 4) forwardly of the machine to rock the gear segments 153 in a counterclockwise direction as viewed in Fig. 4 which in turn move the racks 138 downwardly. It will be understood that the slide 172 has moved downwardly with the head 18 and is, at this time, substantially in alignment with the rod 176 so that there is no appreciable strain on the arm 174 through which pressure is applied to turn the gear segments 152. This downward movement of the racks 138 forces the wipers 22 under heavy pressure against the lasting margin on the crimping plate 28 as the back part is molded under heavy pressure.

The valve 596 which is coupled to the valve 594 includes a pair of ports D and E which communicate with a pressure chamber 694. This chamber is in constant communication with the passageway 584 of the distributor 512 by way of a port G (Fig. 6) and a peripheral passageway 696 in the outer wall of the valve. The valve also includes a discharge chamber 698 which is always in communication with the sump by way of a passageway 700. Ports D' and E' provide communication between the discharge chamber 698 of the valve and passageways 702 and 704, respectively (Figs. 6, 17 and 18), with pipes 398 and 366 leading to the cylinder 276 (Fig. 4). Accordingly, no pressure is applied at this time to the chamber 276 so that it remains in the position shown in Fig. 4.

After the valves 594 and 596 have been rotated in the direction of the arrows (Figs. 14 to 18) by the motor 592 through slightly more than 80° as indicated by the chart, Fig. 23, the port B provides communication between the pressure chamber 654 of the valve 594 by way of the passageway 688 with the space below the piston 669 (Figs. 6 and 11). At the same time the fluid in the space above the piston 668 discharges through passageways 680, 688, 699, port C' of the valve 594 and the discharge chamber 682. Accordingly, the pistons 668 and 669 move upwardly and act through the arm 663 (Fig. 4), bell crank lever

186 and rod 176 to open the wipers slightly to relieve the pressure on the lasting margin. After the pressure has thus been relieved, the port E (Fig. 18) of the valve 596 provides communication between the pressure chamber 694 and the passageway 704 to apply pressure through the pipe 366 to the space behind the small piston 294 (Fig. 4). Inasmuch as there is considerable pressure between the inner and outer molds, the piston 294 remains stationary by reason of the fact that it cannot move horizontally relatively to the inner mold 24. Accordingly, the cylinder housing 276 will move rearwardly carrying the crimping plate 28 away from the inner mold and out of register with the wiper plates 22. The valve 376 in the large piston 292 is moved toward the left by the pressure behind the small piston to permit rapid flow of the oil in front of the large piston through the piston and to the sump, thereby permitting rapid rearward movement of the crimping plate. The pressure behind the small piston 294 is then cut off as indicated by Fig. 28, at which time the valve 594 has moved to a position in which port B' permits discharge of oil from the space below the piston 669 (Fig. 6) and port C' permits application of pressure above the upper piston 668 to cause downward movement of the wipers.

The racks 138 (Fig. 9) move downwardly to move the wipers toward each other and also cause upward movement of the floating rack 150. At the beginning of this movement the rack is in a position above that indicated in Fig. 9 due to a previous downward movement of the wipers to a position below that illustrated, and will move only a short distance before its upper end engages the stop screw 202 at which time the rack is locked in place by the latch 204. As the racks 138 continue to move downwardly, thus moving the wipers inwardly toward each other, the gears 144 will move bodily downwardly inasmuch as the rack 150 is now fixed against movement. This will cause the plate 116 carrying the gears to move downwardly, thus moving the wipers bodily downwardly as they are moved inwardly. The wipers thus turn in the lasting margin against the rear wall of the inner mold 24 to form an attaching flange. The latch 204 prevents downward movement of the floating rack 150 during this time, which might otherwise occur after the flange has been partially turned in with the result that the plate 116 and the wipers would descend more rapidly than desired.

After the wipers have turned in the flange, the port D of the valve 596 provides communication between the pressure chamber 694 of the valve and the pipe 390 so that pressure is now applied ahead of the large piston 292 (Fig. 4). This causes the cylinder chamber 276 to move forwardly until the crimping plate engages the rear surfaces of the wipers 22 and can move no farther. The fluid behind the small piston 294 is, at this time, discharging through pipe 366 and port E' into the discharge chamber 698 of the valve 596 and the spring 384 (Fig. 4) maintains the valve 376 in the large piston closed. After the crimping plate has moved forwardly as far as it can, the increase in pressure in the chamber 296 finally overcomes the resistance between the inner and outer molds, the pressure between which is now starting to drop as will be explained, so that the piston 292 moves rearwardly carrying the inner mold with it to apply heavy pressure between the

flange and the wiper plates 22, thus molding the flange.

Rotation of the valves 594 and 596 by the motor 592 brings the port A' of the valve 594 into communication with the passageway 496 through which pressure has been applied to lift the jack which carries the inner mold 24. This port is of small size, as shown in Fig. 14, so that the pressure is relieved gradually from below the valve 486 (Fig. 6). This port communicates with the passageway 496 by the time that the crimping plate has moved forwardly into engagement with the rearward surfaces of the wiper plates so that the pressure between the molds drops gradually to permit rearward movement of the inner mold. After molding pressure on the flange has been applied for a sufficient time, depending upon the size of the port A', the pressure between the pistons 230 and 44 and below the valve 486 will have dropped sufficiently to permit the valve to be closed by the spring 490 to permit rapid reduction in pressure below the jack piston 230 by way of the port 502 and the pipe 482. By the time that the valve 486 closes, the port D of the rotary valve 596 is closed to the passageway 102 leading to the pipe 390.

At this time, the cam 632 (Fig. 6) has been moved by the piston 612 of the motor 592, to depress the rod 636, thereby retracting the latch 456, thus permitting the valve sleeve 416 to return to the position shown in Fig. 7. The pump, accordingly, discharges directly to the sump through the valve 406, thus relieving the pressure above the small pistons 392 and 394 to permit upward movement of the head by the springs 46. The rod 568 (Fig. 3), accordingly, moves away from the pin 566 carried by the lever 534, thus permitting the valve 510 (Fig. 7) to move to its initial position whereupon the fluid in the distributor chamber 512 discharges to the sump through port 530 and pipe 532. The pressure of the fluid acting on the piston 612 of the motor 592 is thus relieved and the piston is returned to its starting position by the spring 614. This movement of the piston moves the valves 594 and 596 back to their starting positions ready for the next cycle of operation. Inasmuch as there is no fluid under pressure acting on any part of the machine at this time, the various parts are returned to the positions shown in Figs. 1 and 2.

The pump 414 (Fig. 2) is connected by a pipe 710 to a pressure relief valve 712 which permits discharge of fluid through a pipe 714 (Fig. 1) directly to the sump when the pressure in the system exceeds a predetermined value. This pressure may be readily adjusted by a hand wheel 716 of the valve 712 in a well known manner. Connected to the pipe 710 leading to the pressure relief valve 712 is a pipe 718 to which is connected a gauge 720 for indicating the pressure in the system. A belt 722 (Fig. 2) connects the pump to any suitable driving means.

Provision is made for imparting a heightwise tension to the back part after it has been placed over the inner mold 24 to eliminate any possibility of the back part being displaced before pressure has been applied thereto. For this purpose pairs of gripper jaws 730 and 732 (Figs. 3 and 8) are arranged to grip the lasting margin of the upper at opposite sides near the shank. The jaws 732 are mounted at the upper ends of arms 733 and the jaws 730 are mounted at the upper ends of arms 734 of spring material, projecting outwardly and upwardly from the arms 733, the jaws 730 normally being maintained in spaced rela-

tion to the jaws 732 to facilitate placing the work therebetween. Projecting laterally from outer sides of the arms 733 are brackets 736 to the outer portions of which are pivoted at 737 arms 738 provided with thumb portions 740 to facilitate swinging the arms about their pivots. Carried by the arms 738 are cams 741 arranged upon movement of the arms from the positions shown in Fig. 3 to the positions shown in Fig. 8 to move the gripper jaws 730 toward the jaws 732 to clamp the upper therebetween. The lower ends of the arms 733 are pivoted to a bracket 743 which is adjustably connected by a screw-and-slot connection 742 (Fig. 4) to a lever 744, the inner end of which is pivoted at 746 to a bracket 748 fixed to the frame of the machine. The arms 733 and the arms 734 carried thereby are urged by a spring 747 acting between the jack 26 and a pin 749 carried by the arms 733 to the position shown in Fig. 4. This position is determined by engagement of adjustable stop screws 751 threaded through the brackets 736 with the frame of the machine. The lever 744 is provided with a hand grip 750 whereby a downward force may be applied to the lever to move the grippers downwardly to apply a heightwise tension to the upper. The pivotal connection of the arms 733 to the lever 744 permits the grippers to move in a vertical path as the lever is moved downwardly about its pivot.

An arm 752 pivoted at its upper end at 754 to the lever 744 is provided at its lower end with teeth 756. The lower end of the arm extends loosely through a bracket 758 fixed to the frame of the machine. A spring-pressed plunger 760 in the bracket urges the lower end of the arm into engagement with a pawl 762 having a vertical shank portion 764 slidably received in the bracket 758. This pawl is urged downwardly by a spring 766 to a position determined by nuts 768 which engage the upper surface of the bracket 758 and are threaded onto the shank portion of the pawl. As the lever 744 carrying the grippers is moved downwardly it will be locked in any desired position by the engagement of the teeth in the depending arm 756 with the pawl 762. This pawl may move upwardly against the force of the spring 766 during the operation of the machine upon upward movement of the inner mold 24 to limit the tension on the upper and prevent damage thereto. In order to raise the lever 744 at the conclusion of the molding operation, a handle 770 is secured to the depending arm 752 to permit movement of the arm against the force exerted by the spring-pressed plunger 760 to move the teeth 756 out of engagement with the pawl 762 whereupon the lever 744 may be raised to any desired position.

Tension may be applied to the throat of the upper, if desired, by a resilient horn 772 secured at 774 to the jack 26 and extending upwardly and forwardly of the machine. When the upper is presented to the machine, this horn may be pushed rearwardly until the upper has been secured within the grippers after which the resiliency of the horn will cause it to move forwardly so that it will exert pressure on the throat of the upper, thereby assisting in maintaining the upper free of wrinkles.

In the operation of the machine an upper U (Fig. 8) is presented to the machine with its back B placed over the inner mold 24. The bottom edge of the back part is placed against the gage 268 which thereby determines the width of the lasting margin and the gage 256 at the

forward portion of the inner mold assists the operator in centrally disposing the back seam on the mold. The lining grippers 330 are spaced from the crimping plate, as shown in Fig. 10, when the machine is at rest to facilitate insertion of the lining between the grippers and the crimping plate. The lasting margin at the shank portion is placed between the grippers 730 and 732 which are initially in the positions shown in Fig. 3 and the arms 738 are then moved to the positions of Fig. 8 to grip the upper at opposite sides thereof. The lever 750 (Fig. 4) is now moved downwardly to apply the desired amount of tension to the upper and the lining grippers are rendered active by depressing the thumb pieces 354 (Fig. 8). The work is now held on the inner mold under tension and there is no danger that it will be accidentally displaced during the operation of the machine.

The treadle 422 is now depressed, thus moving the valve sleeve 416 (Figs. 6 and 7) to the right to permit the application of pressure above the pistons 392 and 394 (Fig. 5). This causes downward movement of the head against the action of the springs 46 to move the outer mold 28 (Fig. 4) and the wipers 22 downwardly. The wipers 22 first engage the lasting margin of the upper which is disposed on the crimping plate after which the outer mold 28 moves downwardly relatively to the wipers to clamp the back part on the inner mold 24. This downward movement of the outer mold relatively to the wipers continues until the surface 179 of the wipers-supporting slide 62 engages the adjacent surface of the wipers. During the downward movement of the outer mold relatively to the wipers the gear segments 158 (Fig. 9) and the racks 138 move downwardly thereby causing movement of the wipers toward each other firmly to grip the lasting margin on the crimping plate, corrugating the lasting margin to facilitate the subsequent formation of a flange. After the outer mold 28 can move downwardly no farther relatively to the wipers, the head 19 comes to rest inasmuch as the pressure exerted on the small pistons 392 and 394 as determined by the relief valve 712 is insufficient to move the head downwardly against the combined force of the springs 46 which tend to hold the head upwardly and the springs 73 which tend to maintain the head and the outer mold separated. During this portion of the cycle of operation the inner mold 24 (Fig. 4) is somewhat lower than the crimping plate 28 and it should be noted that the forward edges of the crimping plate (Fig. 9) are beveled at 180 on opposite sides of the top portion to eliminate sharp edges which might damage the upper. The crimping plate has a greater radius of curvature than the inner mold so that the lasting margin is stretched relatively to the rest of the back part to eliminate vertically extending wrinkles known as pin wrinkles extending upwardly from the heel seat line which would impair the appearance of the back part. Excessive stretching at the heel seat line would thus occur if the edges were not beveled at 180.

The continued operation of the machine is controlled by downward movement of the lever 534 (Fig. 2) which may be moved automatically or manually, depending upon the position of the pin 566 (Fig. 3). If the pin is in the position illustrated, the rod 568, movable with the head, operates the lever automatically and the valve 510 (Fig. 7) is moved toward the right so that

fluid under pressure flows into the distributing chamber 512. Fluid under pressure immediately flows through the valve 594 and port A, as indicated graphically by the chart in Fig. 23, under the jack-supporting piston 230 by way of the valve 484 which is opened by pressure under the valve member 486. The jack now moves upwardly to move the inner mold vertically and stretch the back part relatively to the lasting margin to define the heel-seat line around the back end. At the same time the pressure is effective to move the large piston 44 connected to the head downwardly so that the head moves downwardly as the inner mold moves upwardly thereby compressing the springs 78 tending to separate the head and the outer mold. This downward movement of the head acts through the cam rolls 84 (Fig. 3) to move the portions of the outer mold toward one another to exert molding pressure on the back part of the upper at the heel end and along the sides, thereby to impart the shape of the inner mold to the back part. During this operation additional pressure is exerted on the wipers to crimp the lasting margin. Fluid under pressure flows by way of port C of the valve 594 (Fig. 6) above the piston 668 to pull the rods 660 downwardly and move the rod 176 (Fig. 4) forwardly to rock the gear segments in a counterclockwise direction. This moves the racks 138 (Fig. 9) downwardly so that the wipers move toward each other until the lasting margin is gripped between the wipers and the crimping plate under relatively heavy pressure. At this stage the back part is molded to final shape on the outer surface of the inner mold 24, the heel-seat line has been defined, and the lasting margin has been crimped and formed to the shape of the crimping plate.

Fluid under pressure during this time has been operating the motor 592 (Fig. 13) to rotate the valves 594 and 596 in the direction of the arrows (Figs. 14 to 18). Referring again to Fig. 23 fluid pressure is now admitted through port B of the valve 594 (Fig. 15) under the piston 669 and the pressure above the piston 668 is now relieved through the discharge port C' of the valve. The pistons now move upwardly to open the wipers slightly and relieve the pressure on the lasting margin. After the wipers have been moved away from the crimping plate, the crimping plate is retracted through the application of pressure by way of port E in valve 596 and pipe 366 to the space behind the small piston 294 (Fig. 4), causing the cylinder housing 276 to move rearwardly relatively to the piston 294 until the crimping plate is out of register with the wipers. Pressure is again applied above the piston 668 (Fig. 4) to move the rods 660 downwardly and through the rod 176 to rock the gear segments 158 in a counterclockwise direction (Fig. 9). The racks 138 are now moved downwardly and the floating rack 150 is simultaneously moved upwardly until it engages the stop screw 202. During this time the wipers have been moving in toward each other but after the floating rack 150 can rise no farther the gears 142 move downwardly bodily to lower the wiper supporting plate 116 so that the wipers will move bodily downwardly simultaneously with their inward movements. The floating rack 150 is locked in its uppermost position by the latch 204 so that after the wipers have turned in the lasting margin against the rearward surface of the inner mold and resistance to their downward movement decreases, the floating rack 150

will not permit the wiper supporting plate 116 to drop faster than permitted by the racks 138.

After the flange has thus been formed pressure is applied through port D of the valve 596 through the pipe 390 (Fig. 4) to move the cylinder housing 276 and the crimping plate 28 forwardly until the crimping plate engages the rear surfaces of the wipers. During this time the small discharge port A' (Fig. 14) of the valve 594 permits gradual discharge of pressure from between the pistons 44 and 230 (Fig. 6) so that the pressure is gradually relieved between the molds. This relief of pressure permits rearward movement of the piston member 290 (Fig. 4) after the crimping plate has moved forwardly into engagement with the wipers. Thus the inner mold 24 is moved rearwardly to exert molding pressure on the flange between the inner mold and the wipers. After this pressure has been exerted for a sufficient length of time, the pressure under the jack will have dropped sufficiently to permit closing of the valve 484 (Fig. 6) so that the pressure between the pistons 44 and 230 rapidly drops and the jack returns to its original position. The valve 510 (Fig. 7) moves back to the position shown under the force exerted by the springs 528 (Fig. 2) and the spring 529 (Fig. 6). During this time the cam 632 associated with the motor 592 which operates the rotary valves releases the latch 456 so that the valve 406 (Fig. 7) returns to the position illustrated. Accordingly the pressure within the distributor chamber and above the pistons 392 and 394 which depress the head is relieved and all the operating parts of the machine return to their starting positions.

While the two-part outer mold which has been described heretofore is generally satisfactory, when the machine is operating on certain kinds of work the leather may be pinched by the adjacent edges of the portions of the mold, thus forming a vertically extending ridge on the outer surface of the back part which impairs the appearance of the finished shoe. To overcome this difficulty, an outer mold 800 made of one solid piece, as illustrated in Figs. 19, 20 and 21, may be provided in place of the two-part mold 20. A pair of vertically extending ears 802 extend upwardly from the mold into recesses formed in the support 60. The ears 802 are secured to the support by pins 804. The mold is curved sharply at its rearward end so that it conforms substantially to the shape of a last and the walls diverge from the rearward end to provide clearance between the inner and outer molds as they are moved together to mold a back part on the inner mold 24. The inner mold, at least for a substantial portion of its length, is shaped complementally to the outer mold so that when the molds are moved together the back part placed between them will be molded to substantially the shape of the inner mold. While the walls of the outer mold are quite rigid they may be moved slightly toward each other to exert a molding action along the forward portions of the back part upon relative movement of the outer mold and the cam rolls 84 which act on cam surfaces 82 similar to those employed with the two-part mold. It will be obvious that if it is not desired to impart final shape to the forward portions of the back part the cam rolls 84 may be omitted and because of the complementary shapes of the inner and outer molds the rearmost portion of the back part will be molded substantially to final shape. The diverging arrangement of the walls of the outer mold is

illustrated clearly in Figs. 20 and 21 and it will be seen that all longitudinal sections of the outer mold have diverging walls throughout substantially their entire lengths. The portion of the outer mold which engages the top of the back part is indicated at 806 in Fig. 20 and the widest longitudinal section of the outer mold is indicated by the lines 808 in Figs. 20 and 21. The line 810 indicates the portion of the outer mold which engages the back part adjacent to the heel seat. It will be obvious from an inspection of Figs. 20 and 21 that there is sufficient clearance between the outer mold and all corresponding portions of the inner mold to permit movement of the molds together without exerting any drag on the sides of the back part. If the machine is to be used for molding separate back parts the lengths of the inner and outer molds may be decreased to whatever extent is desirable and the molding may be effected without exerting any inward pressure on the sides of the outer mold.

Referring now to Fig. 22, there is illustrated a modified form of the machine in which the inner mold is in a position forward of and out of register with the outer mold when the machine is at rest. By so positioning the inner mold when the machine is at rest, the positioning of the work thereon is facilitated inasmuch as no part of the machine is located directly above the inner mold to obscure the operator's vision.

The piston member 280 which is locked to the inner mold-supporting plate 246 against relative horizontal movement is connected by a lever 820 to the fixed arm 314 depending from the bearing 178. A rod 822 is pivotally connected by a yoke 823 and a pin 824 to the lever 820 and extends through a bushing 826 for sliding movement. The bushing is secured to the casing by a screw 827. A spring 828 surrounding the rod 822 acts between a flange 830 on the yoke 823 and a flange 832 on the bushing to urge the lever 820 forwardly of the machine about its pivot 312. This spring accordingly urges the piston member 280 and the inner mold 24 forwardly of the machine so that the inner mold assumes the position illustrated in Fig. 19 when the machine is at rest. The spring 322 causes the cylinder 276 to move with the piston, so that the inner mold and crimping plate move as a unit. The forward position of the inner mold is determined by the engagement of a cam roll 834, mounted at the end of an arm 836 projecting forwardly from the lever 820, with the bottom surface of a cam 838 secured to the plate 39 for vertical movement with the head 18. Upon downward movement of the head at the beginning of the cycle of operation of the machine, the cam 838 urges the cam roll 834 downwardly to move the lever 820 rearwardly against the force of the spring 828, thereby moving the piston member 280 and the inner mold rearwardly. This movement of the inner mold will continue as the head moves downwardly until the inner mold is in register with the outer mold, at which time the cam roll 834 will pass around the lower corner of the cam 838 and engage the vertical face thereof so that further downward movement of the head will not cause any movement of the cam roll or the inner mold 24. At this time the cam roll forms a positive stop to prevent forward movement of the inner mold while permitting further rearward movement against the force exerted by the spring 828 during the molding of the flange as heretofore described.

The inner mold is illustrated herein as having a recess 840 formed in its surface for receiving a

plug 842 arranged for vertical movement relatively to the inner mold. The plug includes a depending shank portion 844 movable in a vertical bore in the plug in which is received a spring 846 acting between the inner mold and the shank for urging the plug upwardly to the position illustrated. It will be noted that in this form of the invention the inner mold assumes a position considerably below the crimping plate 28 when the machine is in its loading position so that a back part placed thereon will engage only the crimping plate and the plug 842 of the inner mold. As the outer mold is moved downwardly during the first part of the operation of the machine and the inner mold moves into register therewith, the back part will initially be gripped at the lasting margin between the wipers 22 and the crimping plate 28 and at an intramarginal portion between the plug 842 and the outer mold. When the jack 26 moves upwardly to stretch the back part to define the heel-seat line, the stretching will occur not only along this line but throughout that portion of the back part bridging the plug 842 and the crimping plate 28. It will be understood that the inner mold will rise relatively to the plug as well as relatively to the crimping plate until the plug 842 forms a continuation of the surface of the inner mold. Thus the materials forming the back part may be stretched throughout the previously unsupported portion bridging the plug and the crimping plate beyond their elastic limits so as to form a permanent bulge therein which has no tendency to return to its original unstretched condition.

It will be understood that the inner mold in that form of the invention shown in Figs. 1 to 18 may be formed with a vertically movable plug, as illustrated in Fig. 22, if it is desired to stretch the materials forming the back part throughout a considerable extent. Likewise, the outer mold of Figs. 19 to 21 may be substituted for the two-part mold shown in Fig. 22. Where the inner mold is mounted for movement forwardly of the machine, as in Fig. 22, the tensioning grippers which engage the shank portion of the work may be omitted and the lining grippers illustrated in Fig. 9 may be relied upon to hold the work in the desired position prior to the clamping of the work between the wipers and the crimping plate. It will also be understood that the machine illustrated herein is not limited to molding the back parts of shoe uppers of the type shown in Fig. 8, but may also be employed for molding separate back parts such as are employed in two-part sandal work.

Having thus described my invention, what I claim as new and desire to secure by Letters Patent of the United States is:

1. In a machine for operating on the back parts of shoe uppers, means for supporting the back part of a shoe upper with its lasting margin overhanging the supporting means, means for preforming the lasting margin of the back part while the back part is on the supporting means and while the lasting margin is unflanged, and means for then turning in the preformed lasting margin against the adjacent surface of the supporting means to form an attaching flange.
2. In a machine for operating on the back parts of shoe uppers, means for supporting the back part of a shoe upper with its lasting margin overhanging the supporting means, means for preforming the lasting margin of the back part while the back part is on the supporting means and while the lasting margin is unflanged, means

for then turning in the preformed lasting margin against the adjacent surface of the supporting means to form an attaching flange, and means for applying molding pressure to the attaching flange.

3. In a machine for operating on the back parts of shoe uppers, means for supporting the back part of a shoe upper with its lasting margin unflanged and overhanging the supporting means, means for crimping the unflanged lasting margin of the back part around the heel end while the back part is on the supporting means, and means for turning in the crimped lasting margin against the adjacent surface of the supporting means to form an attaching flange.

4. In a machine for operating on the back parts of shoe uppers, means for supporting the back part of a shoe upper with its lasting margin unflanged and overhanging the supporting means, means for crimping the unflanged lasting margin of the back part around the heel end while the back part is on the supporting means, means for turning in the crimped lasting margin against the adjacent surface of the supporting means to form an attaching flange, and means for applying molding pressure to the attaching flange.

5. In a machine for operating on the back parts of shoe uppers, a support for the back part of a shoe upper, said support being shaped like the heel portion of a last and being arranged to support the back part of a shoe upper with the lasting margin unflanged and overhanging the support, means for applying molding pressure to the back part to conform it to the support, means for preforming the unflanged overhanging lasting margin of the back part while the back part is on the support, and the means for then turning in the preformed lasting margin against the adjacent surface of the support to form an attaching flange.

6. In a machine for operating on the back parts of shoe uppers, means for supporting the back part of a shoe upper with its lasting margin overhanging the supporting means, means for preforming the lasting margin of the back part while the back part is on the supporting means, means for stretching the back part relatively to the lasting margin to define the heel seat line, and means for bending the lasting margin inwardly on the line thus defined to form an attaching flange.

7. In a machine for operating on the back parts of shoe uppers, means for supporting the back part of a shoe upper with its lasting margin overhanging the supporting means, said supporting means being shaped like the back part of a last, means for applying molding pressure to the back part to conform it to the supporting means, means for clamping the lasting margin, and means for moving said supporting means relatively to said clamping means thereby stretching the back part relatively to the lasting margin to define the heel seat line.

8. In a machine for operating on the back parts of shoe uppers, means for supporting the back part of a shoe upper with its lasting margin overhanging the supporting means, said supporting means being shaped like the back part of a last, means for applying molding pressure to the back part to conform it to the supporting means, means for stretching the back part relatively to the lasting margin to define the heel seat line, and means for preforming the lasting margin, and means for bending the lasting margin inwardly

on the line thus defined to form an attaching flange.

9. In a machine for operating on the back parts of shoe uppers, means for supporting the back part of a shoe upper with its lasting margin overhanging the supporting means, said supporting means being shaped like the back part of a last, means for applying molding pressure to the back part to conform it to the supporting means, means for stretching the back part relatively to the lasting margin to define the heel seat line, means for preforming the lasting margin, means for bending the lasting margin inwardly on the line thus formed to form an attaching flange, and means for applying molding pressure to the attaching flange.

10. In a machine for operating on the back parts of shoe uppers, means for supporting the back part of a shoe upper with its lasting margin unflanged and overhanging the supporting means, said supporting means being shaped like the heel portion of a last, means for crimping the unflanged lasting margin of the back part while the back part is on the supporting means, means for turning in the crimped lasting margin against the adjacent surface of the supporting means to form an attaching flange, and means for applying molding pressure to the back part to conform it to the supporting means.

11. In a machine for operating on the back parts of shoe uppers, means for supporting the back part of a shoe upper with its lasting margin unflanged and overhanging the supporting means, said supporting means being shaped like the heel portion of a last, means for crimping the unflanged lasting margin of the back part while the back part is on the supporting means, means for turning in the crimped lasting margin against the adjacent surface of the supporting means to form an attaching flange, and means for applying molding pressure to the back part to conform it to the supporting means, and means for applying molding pressure to the attaching flange.

12. In a machine for operating on the back parts of shoe uppers, means for supporting the back part of a shoe upper with its lasting margin unflanged and overhanging the supporting means, means for crimping the unflanged lasting margin of the back part while the back part is on the supporting means, means for stretching the back part relatively to said unflanged lasting margin to define the heel seat line, and means for bending the lasting margin inwardly along the line thus formed to form an attaching flange.

13. In a machine for operating on the back parts of shoe uppers, means for supporting the back part of a shoe upper with its lasting margin overhanging the supporting means, said supporting means being shaped like the back part of a last, means for molding the back part to impart thereto the shape of the supporting means, means for crimping the lasting margin, means for stretching the back part relatively to the lasting margin to define the heel-seat line, and means for bending the lasting margin inwardly along the line thus formed to form an attaching flange.

14. In a machine for operating on the back parts of shoe uppers, means for supporting the back part of a shoe upper with its lasting margin overhanging the supporting means, said supporting means being shaped like the heel portion of a last, means for applying molding pressure to the back part to conform it to the shape of the supporting means, means for crimping the lasting margin to facilitate the subsequent forma-

tion of an attaching flange, and means for moving said supporting means relatively to said crimping means thereby stretching the back part relatively to the lasting margin to define the heel-seat line.

15. In a machine for operating on the back parts of shoe uppers, means for supporting the back part of a shoe upper with its lasting margin overhanging the supporting means, said supporting means being shaped like the heel portion of a last, means for holding the upper under lengthwise tension on the supporting means, means for applying molding pressure to the back part to conform it to the supporting means, means for crimping the overhanging lasting margin to facilitate the subsequent formation of an attaching flange, and means for moving said supporting means relatively to said crimping means thereby stretching the back part relatively to the attaching flange to define the heel seat line.

16. In a machine for operating on the back parts of shoe uppers, means for supporting the back part of a shoe upper with its lasting margin overhanging the supporting means, said supporting means being shaped like the heel portion of a last, means for holding the upper under lengthwise tension on the supporting means, means for applying molding pressure to the back part to conform it to the supporting means, means for crimping the overhanging lasting margin to facilitate the subsequent formation of an attaching flange, means for turning in the lasting margin against the adjacent surface of the supporting means to form an attaching flange, and means for applying molding pressure to the attaching flange.

17. In a machine for operating on the back parts of shoe uppers, means for supporting the back part of a shoe upper with its lasting margin overhanging the supporting means, members arranged to engage opposite sides of the lasting margin, and means for relatively moving said members first to preform the lasting margin while it is in unflanged condition and then to wipe in the preformed, unflanged lasting margin to form an inturned flange.

18. In a machine for operating on the back parts of shoe uppers, inner and outer molds for shaping the back part of a shoe upper placed therebetween, means for effecting relative movement of said molds to apply molding pressure to the back part, means for turning the lasting margin of the back part to form an attaching flange and for molding the flange, and means operated by and in response to the movement of one of said molds for starting said flanging and molding means in operation.

19. In a machine for operating on the back parts of shoe uppers, inner and outer molds for shaping the back part of a shoe upper placed therebetween, means for effecting relative movement of said molds to apply molding pressure to the back part, means for turning the lasting margin of the back part to form an attaching flange and for molding the flange, and means operative in response to the relative movement of said molds for starting said flanging and molding means in operation, said last-named means including an operator-controlled member movable into different positions to render said last-named means effective or ineffective at will.

20. In a machine for operating on the back parts of shoe uppers, inner and outer molds for shaping the back part of a shoe upper, members associated with said molds arranged upon move-

ment of the outer mold toward the inner mold to grip the lasting margin of the shoe upper, means for moving said outer mold toward said inner mold, means for then moving the inner mold relatively to said members to stretch the back part relatively to the lasting margin, and means operative in response to movement of the outer mold for starting said inner-mold-moving means in operation.

21. In a machine for operating on the back parts of shoe uppers, inner and outer molds for shaping the back part of a shoe upper, members associated with said molds arranged upon movement of the outer mold toward the inner mold to grip the lasting margin of the shoe upper, means for moving said outer mold toward said inner mold, means for then moving the inner mold relatively to said members to stretch the back part relatively to the lasting margin, and means operative in response to movement of the outer mold toward the inner mold for starting said inner-mold-moving means in operation, said last-named means including an operator-controlled member movable into different positions to render said last-named means effective or ineffective at will.

22. In a machine for operating on the back parts of shoe uppers, inner and outer molds, fluid-pressure means for effecting relative movement of said molds to shape a back part placed therebetween, means for flanging the back part and for molding the flange, fluid-pressure means for operating said flanging and molding means, and a valve operated by movement of one of the molds toward the other for connecting said last-named fluid-pressure means and a source of supply of fluid under pressure.

23. In a machine for operating on the back parts of shoe uppers, inner and outer molds, fluid-pressure means for effecting relative movement of said molds to shape a back part placed therebetween, means for flanging the back part and for molding the flange, fluid-pressure means for operating said flanging and molding means, a valve for controlling the flow of pressure fluid to said last-named fluid-pressure means, means operative in response to the relative movement of said molds for moving said valve to open position, and means under control of the operator for rendering said valve-operating means operative or inoperative at will.

24. In a machine for operating on the back parts of shoe uppers, inner and outer molds, means for moving the outer mold toward the inner mold to shape the back part of a shoe upper placed therebetween, members associated with said molds and arranged upon movement of the outer mold toward the inner mold to grip the lasting margin of the back part, fluid-pressure means for moving the said inner mold relatively to said members to stretch the back part relatively to the lasting margin, a valve for controlling the flow of pressure fluid to said last-named fluid-pressure means, and automatic means for operating said valve at a predetermined time in the downward movement of the outer mold.

25. In a machine for operating on the back parts of shoe uppers, inner and outer molds, means for moving the outer mold toward the inner mold to shape the back part of a shoe upper placed therebetween, members associated with said molds and arranged upon movement of the outer mold toward the inner mold to grip the lasting margin of the back part, fluid-pressure means for moving the inner mold relatively to

said members to stretch the back part relatively to the lasting margin, a valve for controlling the flow of pressure fluid to said last-named fluid-pressure means, and automatic means for operating said valve at a predetermined time in the downward movement of the outer mold, said automatic means including a member movable by the operator at will to render said automatic means inoperative and thus to cause the machine to come to a stop at a definite point in its cycle for the inspection of the work.

26. In a machine for operating on the back parts of shoe uppers, inner and outer molds, fluid-pressure means for moving the outer mold toward the inner mold to shape the back part of a shoe upper placed therebetween, members associated with said molds and arranged upon movement of the outer mold toward the inner mold to grip the lasting margin of the back part, fluid-pressure means for moving the inner mold relatively to said members to stretch the back part relatively to the lasting margin, a valve for controlling the flow of pressure fluid to said last-named fluid-pressure means, means movable with the outer mold for operating said valve, and means under control of the operator for rendering said last-named means operative or inoperative at will.

27. In a machine for operating on the back parts of shoe uppers, an inner mold, an outer mold cooperating with the inner mold to shape a back part placed therebetween, fluid-pressure means for effecting relative movement of said molds, crimping and flanging means associated with said molds, and fluid-pressure means for operating said last-named means to crimp the lasting margin of the back part and to turn it inwardly against a face of the inner mold to form an attaching flange.

28. In a machine for operating on the back parts of shoe uppers, an inner mold, an outer mold cooperating with the inner mold to shape a back part placed therebetween, fluid-pressure means for effecting relative movement of said molds, means associated with said molds for crimping the marginal portion of the back part and for turning it inwardly against one face of the inner mold to form an attaching flange, fluid-pressure means for operating said crimping and flanging means to crimp the margin of the back part and to form the attaching flange, valve means for controlling the flow of fluid under pressure to said last-named fluid-pressure means, and fluid-pressure-operated means for operating said valve means.

29. In a machine for operating on the back parts of shoe uppers, an inner mold and an outer mold relatively movable to shape the back part of a shoe upper, means associated with said molds for crimping the marginal portion of the back part and for wiping it inwardly over one face of said inner mold to form an attaching flange on the back part, fluid-pressure means for operating said crimping and flanging means, valve means for controlling the flow of pressure fluid to said fluid-pressure means to cause the crimping and flanging operations to be performed in predetermined time relation, and fluid-operated means for operating said valve means.

30. In a machine for operating on the back parts of shoe uppers, an inner mold and an outer mold relatively movable to shape the back part of a shoe upper, parts associated with said molds for crimping the marginal portion of the back part and for wiping it inwardly over one face of

the inner mold to form an attaching flange on the back part, and fluid-pressure means for thus operating said parts including a valve movable to connect said fluid-pressure means with a source of pressure fluid in response to relative movement of said inner and outer molds.

31. In a machine for operating on the back parts of shoe uppers, means for supporting the back part of a shoe upper with its lasting margin overhanging the supporting means, members arranged to engage opposite sides of the lasting margin, means for relatively moving said members first to preform the lasting margin while it is in unflanged condition and then to wipe in the lasting margin to form an inturned flange, and means for relatively moving the supporting means and one of said members to mold the inturned flange.

32. In a machine for operating on the back parts of shoe uppers, means for supporting the back part of a shoe upper with its lasting margin unflanged and overhanging the supporting means, said supporting means being shaped like the heel portion of a last, means cooperating with said supporting means to mold the back part substantially to final shape, inner and outer lasting-margin-engaging members, and means for relatively moving said members first to crimp the unflanged lasting margin and then to wipe in the lasting margin to form an inturned flange.

33. In a machine for operating on the back parts of shoe uppers, means for supporting the back part of a shoe upper with its lasting margin unflanged and overhanging the supporting means, said supporting means being shaped like the heel portion of a last, means cooperating with said supporting means to mold the back part substantially to final shape, inner and outer lasting-margin-engaging members, means for relatively moving said members first to crimp the unflanged lasting margin and then to wipe in the lasting margin to form an inturned flange, and means for relatively moving the supporting means and the inner member to mold the flange thus formed.

34. In a machine for operating on the back parts of shoe uppers, means for supporting the back part of a shoe upper with its lasting margin overhanging the supporting means, means for gripping the opposite sides of the lasting margin at the extreme heel end portion of the back part, and means for relatively moving said supporting means and said gripping means rearwardly of the back part to stretch the back part relatively to the lasting margin to define the heel-seat line.

35. In a machine for operating on the back parts of shoe uppers, means for supporting the back part of a shoe upper with its lasting margin overhanging the supporting means, said supporting means being shaped like the heel portion of a last, members arranged to engage opposite sides of the lasting margin to preform it, means for moving said supporting means relative to said members to stretch the back part relatively to the lasting margin to define the heel-seat line, and means cooperating with said supporting means to mold the back part substantially to final shape.

36. In a machine for operating on the back parts of shoe uppers, means for supporting the back part of a shoe upper with its lasting margin overhanging the supporting means, members arranged to engage opposite sides of the lasting

margin, means for relatively moving said members first to preform the lasting margin and then to wipe in the lasting margin to form an in-turned flange, and means for moving said support relatively to said members before the flange has been turned in to stretch the back part relatively to the lasting margin to define the heel-seat line.

37. In a machine for operating on the back parts of shoe uppers, means for supporting the back part of a shoe upper with its lasting margin overhanging the supporting means, said supporting means being shaped to conform to the back part of the last, means cooperating with said supporting means to mold the back part substantially to final shape, members arranged to engage opposite sides of the lasting margin, means for relatively moving said members first to crimp the lasting margin and then to wipe in the lasting margin to form an in-turned flange, and means for relatively moving said supporting means and said members prior to wiping in the lasting margin to define the heel-seat line.

38. In a machine for operating on the back parts of shoe uppers, a support for the back part of a shoe upper with its lasting margin overhanging the support, inner and outer crimping members arranged to engage opposite sides of the lasting margin, means for relatively moving said members to crimp the lasting margin, means for thereafter moving the inner crimping member out of register with the lasting margin, and means for then moving the outer crimping members to turn in the lasting margin of the back part to form an attaching flange.

39. In a machine for operating on the back parts of shoe uppers, a support for the back part of a shoe upper with its lasting margin overhanging the support, an inner crimping member and a pair of outer crimping members arranged to engage opposite sides of the lasting margin, means for moving the outer members toward the inner member to crimp the lasting margin, means for thereafter moving the inner crimping member out of register with the lasting margin, means for then moving the outer crimping members to turn in the lasting margin of the back part to form an attaching flange, and means for applying molding pressure between said supporting means and the outer crimping members to mold the flange.

40. In a machine for operating on the back parts of shoe uppers, a support for the back part of a shoe upper with its lasting margin overhanging the support, an inner crimping member and a pair of outer crimping members arranged to engage opposite sides of the lasting margin, means for relatively moving said members to crimp the lasting margin, means for thereafter moving the inner crimping member out of register with the lasting margin, means for then moving the outer crimping members to turn in the lasting margin of the back part to form an attaching flange, and means for causing relative movement between said support and said outer members to exert pressure therebetween to mold the flange.

41. In a machine for operating on the back parts of shoe uppers, an inner mold shaped like the back part of a last and arranged to support the back part of a shoe upper with its lasting margin overhanging the mold, an outer mold movable toward the inner mold to shape the back part, a crimping member associated with the inner mold and movable toward and away from said mold, crimping means associated with the outer mold, means for moving the outer mold and associated crimping means toward the inner mold to shape the back part and crimp the lasting margin, means for moving the inner crimping member away from the inner mold, and means for then moving the outer crimping means to turn in the lasting margin to form an attaching flange.

42. In a machine for operating on the back parts of shoe uppers, an inner mold shaped like the back part of a last and arranged to support the back part of a shoe upper with its lasting margin overhanging the mold, an outer mold arranged to cooperate with the inner mold to shape the back part, a crimping member associated with the inner mold, crimping means associated with the outer mold, means for moving the outer mold and associated crimping means toward the inner mold to shape the back part and crimp the lasting margin, and means for moving the inner mold rearwardly of the upper supported thereon to stretch the back part relatively to the lasting margin to define the heel-seat line.

43. In a machine for operating on the back parts of shoe uppers, an inner mold shaped like the back part of a last and arranged to support the back part of a shoe upper with its lasting margin overhanging the mold, an outer mold arranged to cooperate with the inner mold to shape the back part, a crimping member associated with the inner mold, crimping means associated with the outer mold, means for moving the outer mold and associated crimping means toward the inner mold to shape the back part and crimp the lasting margin, means for moving the inner mold rearwardly of the upper supported thereon to stretch the back part relatively to the lasting margin to define the heel-seat line.

44. In a machine for operating on the back parts of shoe uppers, an inner mold shaped like the back part of a last and arranged to support the back part of a shoe upper with its lasting margin overhanging the mold, an outer mold arranged to cooperate with the inner mold to shape the back part, a crimping member associated with the inner mold, crimping means associated with the outer mold, means for moving the outer mold and associated crimping means toward the inner mold to shape the back part and crimp the lasting margin, means for moving the inner mold rearwardly of the upper supported thereon to stretch the back part relatively to the lasting margin and define the heel-seat line, means for moving the inner crimping member away from the inner mold, and means for then moving the outer crimping means to turn in the lasting margin and form an attaching flange.

45. In a machine for operating on the back parts of shoe uppers, an inner mold, an outer mold cooperating with the inner mold to shape a back part placed therebetween, fluid-pressure means for effecting relative movement of said molds, crimping and flanging means associated with said molds, fluid-pressure means for operating said last-named means to crimp the last-

ing margin of the back part and to turn it inwardly against a face of the inner mold to form an attaching flange, rotary valve means for controlling the application of fluid under pressure to said last-named fluid-pressure means to cause the crimping and flanging operations to be performed in predetermined time relation, a fluid-pressure member for operating said rotary valve means, and means controlled by movement of one of the molds toward the other for connecting said fluid-pressure member and said valve means to a source of supply of fluid under pressure.

46. In a machine for operating on the back parts of shoe uppers, an inner mold, an outer mold cooperating with said inner mold to shape a back part placed therebetween, fluid-pressure means for effecting relative movement of said molds, wipers associated with said outer mold for turning the lasting margin of the back part against a face of the inner mold to form an attaching flange, fluid-pressure means for operating said wipers, and different valves for controlling the flow of pressure fluid to said different fluid-pressure means, one of said valves being controlled manually and the other automatically at a predetermined time in the relative movement of said molds.

47. In a machine for operating on the back parts of shoe uppers, an inner mold, an outer mold cooperating with said inner mold to shape a back part placed therebetween, fluid-pressure means for effecting relative movement of said molds, wipers associated with said outer mold for turning the lasting margin of the back part against a face of the inner mold to form an attaching flange, fluid-pressure means for operating said wipers, a first valve for controlling the flow of fluid under pressure to said first-named fluid-pressure means, a second valve for controlling the flow of fluid under pressure to said last-named fluid-pressure means, treadle-operated means for moving the first valve to open position, a spring urging said valve out of said position, means for locking said valve in open position against the resistance of said spring, and means for automatically operating said locking means to release the valve to the action of said spring after a predetermined time following movement of the second valve to pressure-applying position.

48. In a machine for operating on the back parts of shoe uppers, inner and outer molds, fluid-pressure means for effecting relative movement of said molds to shape a back part placed therebetween, a valve movable to a position in which fluid under pressure flows to said fluid-pressure means, fluid-pressure-operated means for crimping the lasting margin and turning the lasting margin inwardly against a face of the inner mold to form an attaching flange, a rotary valve for controlling the flow of pressure fluid to said fluid-pressure-operated means to cause the crimping and flanging operation to occur in predetermined time relation, a fluid-pressure member for operating said rotary valve, means operative in response to relative movement of the molds for conducting fluid under pressure to said rotary valve means and said fluid-pressure member, means operated by said fluid-pressure member at a predetermined time during the operation of the machine for moving the first valve out of pressure-applying position, and means operated in response to such movement

of the valve for causing the return of the other parts of the machine to their original positions.

49. In a machine for operating on the back parts of shoe uppers, an inner mold, an outer mold, fluid-pressure means for effecting relative movement of said molds to shape a back part placed therebetween, an operator-controlled valve movable to a position in which fluid under pressure flows to said fluid-pressure means, means normally maintaining said valve out of said position, a latch for holding the valve in said position against the action of said means, means for flanging the lasting margin of the back part and molding said flange, fluid-pressure means for operating said flanging and molding means, rotary valve means for controlling the flow of pressure fluid to said last-named fluid-pressure means to cause the crimping and flanging operations to occur in predetermined time relation, means operated in response to relative movement of said molds for operating said rotary valve means, and means for moving said latch out of locking position.

50. In a machine for operating on the back parts of shoe uppers, an inner mold, an outer mold, fluid-pressure means for effecting relative movement of said molds to shape a back part placed therebetween, an operator-controlled valve movable to a position in which fluid under pressure flows to said fluid-pressure means, means normally maintaining said valve out of said position, a latch for holding the valve in said position against the action of said means, means for flanging the lasting margin of the back part and molding said flange, fluid-pressure means for operating said flanging and molding means, rotary valve means for controlling the flow of pressure fluid to said last-named fluid-pressure means to cause the crimping and flanging operations to occur in predetermined time relation, means operated in response to relative movement of said molds for operating said rotary valve means, means controlled by the rotary-valve-operating means for moving said latch to permit movement of said first-named valve out of pressure-applying position, and means operated by said movement of said valve for returning the parts of the machine to their original positions.

51. In a machine for operating on the back parts of shoe uppers, an inner mold for supporting a back part with its lasting margin overhanging the mold, a crimping plate associated with said mold and arranged to underlie the lasting margin of the back part, an outer mold movable toward the inner mold to shape the back part, wipers associated with said outer mold and movable therewith, fluid-pressure means for moving the outer mold and wipers toward the inner mold and crimping plate to crimp the lasting margin between the crimping plate and the wipers, fluid-pressure means for moving the inner mold relatively to the crimping plate to stretch the back part relatively to the lasting margin, fluid-pressure means for then opening the wipers, retracting the crimping plate and then closing the wipers to turn in the lasting margin to form an attaching flange and finally to apply molding pressure between the wipers and the inner mold to mold the flange, rotary valve means for controlling said last-named fluid-pressure means, and a fluid-pressure member for operating said valve means.

52. In a machine for operating on the back parts of shoe uppers, an inner mold for supporting a back part with its lasting margin over-

hanging the mold, a crimping plate associated with said mold and arranged to underlie the lasting margin of the back part, an outer mold movable toward the inner mold to shape the back part, wipers associated with said outer mold and movable therewith, fluid-pressure means for moving the outer mold and wipers toward the inner mold and crimping plate to crimp the lasting margin between the crimping plate and the wipers, fluid-pressure means for moving the inner mold relatively to the crimping plate to stretch the back part relatively to the lasting margin, fluid-pressure means for then opening the wipers, retracting the crimping plate and then closing the wipers to turn in the lasting margin to form an attaching flange and finally to apply molding pressure between the wipers and the inner mold to mold the flange, rotary valve means for controlling said last-named fluid-pressure means, a fluid-pressure member for operating said valve means, and means responsive to movement of the outer mold toward the inner mold for conducting fluid under pressure to the fluid-pressure means for moving the inner mold, and to said fluid-pressure member.

53. In a machine for operating on the back parts of shoe uppers, an inner mold for supporting a back part with its lasting margin overhanging the mold, a crimping plate associated with said mold and arranged to underlie the lasting margin of the back part, an outer mold movable toward the inner mold to shape the back part, wipers associated with said outer mold and movable therewith, fluid-pressure means for moving the outer mold and wipers toward the inner mold and crimping plate to crimp the lasting margin between the crimping plate and the wipers, fluid-pressure means for moving the inner mold relatively to the crimping plate to stretch the back part relatively to the lasting margin, fluid-pressure means for then opening the wipers, retracting the crimping plate and then closing the wipers to turn in the lasting margin to form an attaching flange and finally to apply molding pressure between the wipers and the inner mold to mold the flange, rotary valve means for controlling said last-named fluid-pressure means, a fluid-pressure member for operating said valve means, means responsive to movement of the outer mold toward the inner mold for conducting fluid under pressure to the fluid-pressure means for moving the inner mold, and to said fluid-pressure member, and means under the control of the operator for rendering said last-named means operative or inoperative at will.

54. In a machine for operating on the back parts of shoe uppers, an inner mold for supporting a back part with its lasting margin overhanging the mold, a crimping plate associated with said mold and arranged to underlie the lasting margin of the back part, an outer mold movable toward the inner mold to shape the back part, wipers associated with said outer mold and movable therewith, fluid-pressure means for moving the outer mold and wipers toward the inner mold and crimping plate to crimp the lasting margin between the crimping plate and the wipers, fluid-pressure means for moving the inner mold relatively to the crimping plate to stretch the back part relatively to the lasting margin, fluid-pressure means for then opening the wipers, retracting the crimping plate and then closing the wipers to turn in the lasting margin to form an attaching flange and finally to apply molding pressure between the wipers

5 and inner mold to mold the flange, rotary valve means for controlling said last-named fluid pressure means, a fluid-pressure member for operating said valve means, means responsive to movement of the outer mold toward the inner mold for conducting fluid under pressure to the fluid-pressure means for moving the inner mold, and to said fluid-pressure member, and means operated by said fluid-operated member after a predetermined time interval for terminating the operation of the machine and for causing return of the parts to their original positions.

55. In a machine for operating upon the back parts of shoe uppers, a work support shaped like the heel portion of a last, a mold cooperating therewith to mold a back part upon the work support, means mounting said work support for movement into and out of register with said mold, means normally holding said work support out of register with the mold and means for simultaneously moving said work support into register with said mold and moving said mold toward said work support.

56. In a machine for operating upon the back parts of shoe uppers, a work support shaped like the heel portion of a last, a mold cooperating therewith to mold a back part on the work support, means mounting said work support for movement into and out of register with said mold, means normally holding said work support out of register with said mold, means for moving said mold toward said work support, and means operated in response to movement of the mold for simultaneously moving the work support into register therewith.

57. In a machine for operating upon the back parts of shoe uppers, a work support shaped like the heel portion of a last, a mold located above said work support and movable downwardly to 40 mold a back part on the work support, means supporting said work support for movement in a horizontal plane into and out of register with said mold, means normally holding said work support out of register with said mold, means for 45 moving said mold downwardly, and means operated in response to said movement for moving the work support into register therewith, said last-named means being constructed and arranged to terminate movement of the work support after it has been moved into register with the mold.

58. In a machine for operating upon the back parts of shoe uppers, a work support shaped like the heel portion of a last, a mold mounted above said work support and movable downwardly to mold a back part on the work support, means supporting said work support for sliding movement in a horizontal plane, means urging said work support to a position out of register with said mold, a lever connected to said work support, a cam roll carried by said lever, and a cam movable with said mold and constructed and arranged upon movement of said mold downwardly to act on said cam roll and to move the work support into register with the mold.

59. In a machine for operating upon the back parts of shoe uppers, a work support shaped like the heel portion of a last, said work support including a vertically movable plug in an intramarginal portion thereof and movable from a position in which it forms a continuation of the surface of the work support to a position in which it projects outwardly of the surface thereof, means normally holding the plug in said last-

named position, means adjacent to said work support for supporting the lasting margin of the back part in overhanging relation to the support, means for clamping a back part against said plug and the lasting margin against the lasting-margin-supporting means with an intramarginal portion of the back part unsupported, and means for exerting pressure on the back part and causing relative movement between the plug and the work support until the plug forms a continuation of the surface of the work support, thereby to stretch the intramarginal unsupported portion of the back part.

60. In a machine for operating upon the back parts of shoe uppers, a work support shaped like the heel portion of a last, said work support having a recess formed in an intramarginal portion of the heel end thereof, a plug movable in said recess and arranged when in one position to form a smooth, substantially uninterrupted continuation of the surface of the work support, and means urging said plug to a position in which it projects outwardly of the work support.

61. In a machine for operating upon the back parts of shoe uppers, means for supporting the back part of a shoe upper with the lasting margin overhanging the supporting means, said supporting means being shaped like the heel portion of a last, a crimping plate adjacent to said supporting means and being arranged to support the overhanging lasting margin of the back part, means normally urging said crimping plate and said supporting means toward each other, means cooperating with said supporting means and said crimping plate for molding the back part and crimping the lasting margin, and means for separating the crimping plate and the supporting means to permit turning the lasting margin inwardly to form a flange.

62. In a machine for operating upon the back parts of shoe uppers, a support for the back part of a shoe upper, said support being shaped like the heel portion of a last and being arranged to support a back part in depending relation with its lasting margin overhanging the support, a crimping plate movably associated with said work support and arranged to underlie the lasting margin when the crimping plate is adjacent to said support, means urging said crimping plate and said work support toward each other, means for causing relative heightwise movement of said crimping plate and said work support, and means for separating the crimping plate and the work support.

63. In a machine for operating upon the back parts of shoe uppers, a vertically movable jack, a work support carried by said jack for vertical movement therewith and for horizontal movement relatively thereto, a crimping plate associated with said work support for supporting the lasting margin of a back part of a shoe upper carried by the support, said crimping plate being movable horizontally independently of the work support and being constrained against vertical movement, means for moving said jack vertically to move the work support heightwise relatively to said crimping plate, and means for moving the crimping plate toward and away from the work support.

64. In a machine for operating upon the back parts of shoe uppers, a work support shaped like the heel portion of a last and being arranged to support the back part of a shoe upper with the lasting margin overhanging the support, a vertically movable jack, means supporting said work

support on said jack for horizontal movement relatively thereto, a piston carried by said work support for horizontal movement therewith and for vertical movement relatively thereto, a cylinder housing said piston, a crimping plate carried by said cylinder adjacent to said work support and arranged to underlie the lasting margin of a back part on the work support, means for moving said jack vertically to vary the relative heightwise positions of said crimping plate and said work support, and means for alternately introducing fluid under pressure to opposite sides of said piston to move the crimping plate toward and away from said work support according to a predetermined sequence of operations.

65. In a machine for operating upon the back parts of shoe uppers, a work support shaped like the heel portion of a last, a head movable toward and away from the work support, a two-part mold carried by said head for movement toward said work support to mold the back part of a shoe upper supported thereon, said mold being movable relatively to the head, means acting on said mold normally to hold it in spaced relation to the head, means for moving the head to carry the mold toward the work support, a cam carried by each part of the mold, and cam rolls carried by the head cooperating with said cams and arranged in response to movement of the head and mold toward each other to move the parts of the mold inwardly.

66. In a machine for operating upon the back parts of shoe uppers, a work support shaped like the heel portion of a last, a head movable toward and away from the work support, a two-part mold carried by said head for movement toward said work support to mold the back part of a shoe upper supported thereon, said mold being movable relatively to the head, means acting on said mold normally to hold it in spaced relation to the head, means for moving the head to carry the mold toward the work support, a cam carried by each part of the mold, cam rolls, levers carried by said head and supporting said cam rolls, and resilient means acting on said levers to maintain said cam rolls in engagement with the cams on said mold, said cams and cam rolls being arranged upon movement of said head and mold toward one another to urge the portions of the mold inwardly.

67. In a machine for operating upon the back parts of shoe uppers, a work support shaped like the back part of a last, means adjacent to said work support for supporting the unflanged overhanging lasting margin of a back part on the work support, a head movable toward and away from said work support, a mold carried by said head for molding the back part to the shape of the work support, lasting-margin-engaging members carried by said head and movable relatively thereto, said members being arranged to engage the lasting margin prior to the application of full molding pressure on the back part to clamp the unflanged lasting margin on the supporting means, means for moving said head toward said work support, and means operative in response to relative movement of said mold relatively to said members for moving said members inwardly to compress and preform the lasting margin against the supporting means.

68. In a machine for operating upon the back parts of shoe uppers, a work support shaped like the heel portion of a last, a crimping plate associated therewith and arranged to underlie the overhanging lasting margin of the back part of

a shoe upper carried by the support, a head movable toward and away from said work support, a mold carried thereby and arranged upon movement of the head toward the work support to mold the back part thereon, a pair of wipers carried by said head and arranged for movement as a unit relatively thereto and for movement toward and from each other, means urging said wipers for movement with said head, said wipers having crimping surfaces arranged to crimp the margin of the back part in cooperation with said crimping plate, and means operative in response to movement of the head relatively to the wipers for moving the wipers inwardly toward the crimping plate to compress and crimp the unflanged lasting margin.

69. In a machine for operating upon the back parts of shoe uppers, a support for the back part of a shoe upper shaped like the heel portion of a last, a head vertically movable toward and away from said support, a mold carried by the head and cooperating with said support to mold the back part of a shoe upper carried by the support, a crimping plate adjacent to said support underlying the overhanging lasting margin of the back part, a wiper-supporting plate carried by said head and movable vertically relatively thereto, means urging said plate for movement with said head, a pair of wiper members carried by said plate for movement toward and away from each other, said wipers having crimping surfaces arranged to crimp the margin of the back part in cooperation with said crimping plate, means normally maintaining said wipers in widely spaced relation, and means operative in response to downward movement of the head relatively to said wiper-supporting plate for moving said wipers inwardly toward the crimping plate

to compress and crimp the unflanged lasting margin.

70. In a machine for operating upon the back parts of shoe uppers, a support for the back part of a shoe upper shaped like the heel portion of a last, a crimping plate for supporting the overhanging lasting margin of the upper, a head movable vertically toward and away from said support, a two-part mold carried by said head for movement therewith and for vertical movement relatively thereto, a pair of wipers carried by said head and movable as a unit vertically relatively thereto, said wipers also being arranged for movement toward and away from each other, means operative upon downward movement of the head relatively to said mold for moving the parts of the mold toward each other to exert pressure on the sides of a back part mounted on the work support, and means operative upon downward movement of the head relatively to said wipers to move the wipers inwardly toward each other to exert pressure on the lasting margin of the back part on the heel end around the sides thereof.

71. In a counter molding machine, the combination of a cross girt, a one-piece female mold adjustably suspended from the cross girt and having a V-shaped cavity sharply concave at its inner end, and a complementary wedge-shaped plug mounted in the machine for movement in and out of the female mold.

72. In a counter molding machine, a plug with diverging side walls, in combination with a one-piece female mold having a V-shaped cavity with its inner end sharply concaved between the faces of the mold, and all longitudinal sections of the cavity being divergent to provide withdrawing clearance for the plug.

LESTER S. MACDONALD.
